UNITED STATES PATENT OFFICE

2,331,118

SHOE SEWING MACHINE

Joseph Gouldbourn and Thomas Aubrey Kestell,
Leicester, England, assignors to United Shoe
Machinery Corporation, Borough of Flemington,
N. J., a corporation of New Jersey

Application May 20, 1939, Serial No. 274,794
In Great Britain June 28, 1938

75 Claims. (Cl. 112—38)

The present invention is concerned with improvements in or relating to sewing, and to mechanism adapted for use in sewing machines, and is particularly but by no means exclusively, concerned with providing for the improved construction and operation of sewing machines of the type for sewing a sole to a shoe bottom by a seam passing through the sole to the side of the shoe bottom. The term "shoe" is used herein as indicating foot-wear generally.

The invention is herein particularly disclosed as embodied in a lockstitch machine of the so-called McKay type having a hook needle, a rotatably adjustable work supporting horn, and a needle threading device within the horn.

It is an object of the present invention to provide a novel and improved sewing machine of this general description which is well adapted for efficient and accurate operation at very high speeds, and which is so constructed and arranged as to permit a virtually unimpeded visual inspection and a sure control of the work by the operator for high speed sewing.

In accordance with the invention, there is provided a novel organization and arrangement of the several operating instrumentalities to secure a more compact and efficient arrangement of the parts, and to eliminate so far as possible the large mass of parts extending above the work. Features of applicants' machine in accordance with the above noted object include a needle and awl which are pivotally supported on rearwardly extending arms having a substantial radius of movement to cause the needle and awl to follow a substantially straight path through the work, and to cause the needle to cooperate in an efficient manner with the rotatably adjustable horn and needle threading device supported therein. The needle, awl and thread take-up motions of the machine are derived from crank driven lever and link mechanisms.

Other features of the invention in accordance with the above noted object, consist in an improved construction and arrangement of the work engaging instrumentalities to cause the awl to feed the work. Specifically, the needle and awl are supported a fixed distance apart from one another in the line of feed on a feed bracket which is pivotally supported to cause the needle and awl to move back and forth in the line of feed. In the illustrated construction, the feed bracket is mounted to turn about a vertical pivot located rearwardly of the sewing point, being advanced in the line of feed in timed relation to the awl motion to cause the awl to feed the work,

and then in a reverse direction to position the needle in line with the previously formed awl hole.

A further object of the invention is concerned with the provision of an improved arrangement and mode of operation of the thread handling devices for use in McKay and similar type machines which do not have a thread finger or similar device for supplying thread to the needle during its loop drawing stroke, and in which it is therefore desired to provide such a supply of thread to the needle from the preceding stitch. In the illustrative machine, the thread handling devices include a shuttle, a take-up, a thread measuring pull-off, and a pair of thread locks bracketed on opposite sides of the pull-off. The thread handling devices are arranged to cause the shuttle or loop taker to set the previous stitch at substantially the beginning of its loop drawing stroke, the thread lock against which the stitch is set being then opened to permit the passing of the needle loop over the bobbin case.

It is a further object of the invention to improve the construction and mode of operation of the thread handling devices for setting the previous stitch in this manner to cause the stitches of the seam to be set firmly and accurately in the work, and without any tendency toward breaking or stranding of the thread. In accordance with this object, a feature of the invention consists in a construction and arrangement of the stitch forming and setting devices including means arranged during the setting of the previous stitch to provide an accumulation of slack thread to the supply side of the thread lock against which the stitch is set, which is quickly available to be taken up by the shuttle or loop taker during its loop drawing stroke. In the preferred construction, such an accumulation of slack thread is provided by causing the thread measuring pull-off to pull in an amount of thread in excess of that required for the next stitch, and thereafter to give up such additional thread during and subsequent to the setting of the stitch. Further in accordance with the last noted object, a feature of the invention consists in a construction and arrangement of the take-up to cause the take-up to exert a pull on the needle thread passing to the shuttle hook or loop taker while the stitch is being set.

In an alternative form of the invention, the previous stitch is set by the shuttle against a third thread lock interposed between the thread take-up and the work, the take-up being con-

tinuously actuated to give up thread during the stitch setting operation, so that an accumulation of slack thread is provided which is immediately available upon opening of the stitch setting thread lock to be drawn upon by the shuttle during its loop drawing stroke.

Another object of the invention is to provide a novel and improved arrangement and mode of operation of the loop lifter or spreader for causing the loop spreader to engage with and open the loop of needle thread drawn through the work, and to present the spread loop to the loop taker in a most efficient manner, while at the same time causing the loop spreader at all times to operate in a path which at no point crosses the path of movement of the loop taker or shuttle, so that no possibility of injury can arise through mis-timing or faulty operation of the cooperating parts. Applicant's improved loop spreader is pivotally supported to move in a general forward direction to engage with and open the loop of needle thread drawn through the work, and to present the spread loop to the loop taker, said movement including a component movement laterally in the line of feed toward the needle to engage the loop spreader with the needle loop, and thereafter a component movement laterally in the line of feed away from the needle to present the spread loop to the loop taker. In order to effect these movements, the loop taker is preferably supported to turn on an axis located above and extending upwardly to the right at an angle of about 50° to the line of stitching and rearwardly at an angle of about 60° to said line.

It is a further object of the invention to provide an improved construction and arrangement of the shuttle and shuttle raceway to avoid possible injury to the parts through the jamming of thread in the shuttle raceway. A feature of the invention with the last noted object in view, contemplates the provision in a lockstitch sewing machine, of a shuttle rotatable to carry the needle loop over the shuttle, and a shuttle race yieldably supported to permit rotation of the race with the shuttle in the event that the shuttle becomes jammed in the race. In the preferred construction, cooperating cutting edges are provided on the race and its supporting guideway to sever the jammed thread portions. The supporting means for the shuttle race are further constructed and arranged to positively support the race against movement in the reverse direction from its normally stationary position, so that the parts may be readily re-positioned in operating position in the event that thread becomes jammed between the raceway and the shuttle, by manually rotating the shuttle in a reverse direction to reposition the race and to free the jammed thread portion therefrom.

It is another object of the invention to provide a novel and improved arrangement of the mechanism for adjusting the operation of the thread measuring pull-off of the machine in accordance with the thickness of the work. In the preferred form of the invention, the extent of the movement of the pull-off is controlled by means of a power operated mechanism which is in turn controlled through a mechanical relay device adjustable in accordance with the setting of the presser foot and presser foot locking device against the work.

Further in accordance with the invention, a novel and improved pay-off mechanism is employed for insuring a ready and adequate supply

of thread from the supply spool or cop. In the preferred form, this mechanism comprises an oscillating friction pawl acting against a cooperating friction surface supported to turn with the thread mass to rotate the thread cop in a pay-off direction in timed relation to the thread handling device, and alternately to frictionally urge the thread mass in a reverse direction in order to take up any slack thread in the system.

Further objects of the invention relate to improvements in the mechanism for actuating and for controlling the operation of the presser foot during the operation of the machine, and in stopping and starting of the machine. In accordance with the objects last noted, one feature of the invention consists in the provision of mechanism for locking the presser foot against the work and for raising the presser foot during the work feed, constructed and arranged to permit the presser foot to yield a predetermined small distance from its locked position against the work in order to facilitate tilting of the work by the operator to effect any desired adjustment in the position of the seam in the work.

Another feature of the invention consists in the provision of an improved control operable in starting and stopping the machine for moving the presser foot into and out of operative position. The illustrated machine is provided with power means which is rendered operative in stopping the machine to raise the presser foot only after the machine has stopped, and operating connections controlled from the starting treadle of the machine, which are rendered operative by partial movement of the foot treadle to engage the presser foot against the work, and by further movement of the treadle to start the machine, and by the releasing of the foot treadle from either of said positions, to render said power means operative to raise the presser foot independently of whether the machine has actually been started.

It will be understood that while the several features of the present invention are herein disclosed and are particularly applicable to a McKay lockstitch sewing machine provided with a rotatable work supporting horn, certain features of the invention are of more general application to shoe sewing machines of other types, and for operating on other than McKay shoes.

With the above stated and other objects in view, as may hereinafter appear, the several features of the invention consist also in the devices, combinations and arrangement of parts herein-after described and claimed, which together with the advantages to be obtained thereby will be readily understood by one skilled in the art from the following description taken in connection with the accompanying drawings, in which Figure 1 is a right hand side elevation of the illustrative machine; Fig. 2 is a sectional elevation of a horn, shown disconnected, and driving mechanism of the illustrative machine; Fig. 3 is a section on the line 3-3 in Fig. 7; Fig. 4 is a front elevation, partly in section, showing take-up and thread locking mechanisms of the illustrative machine; Fig. 5 is a side elevation, partly in section, of a head of the illustrative machine; Fig. 6 is a plan view, partly in section, illustrating work feeding mechanism of the illustrative machine; Fig. 7 is a side elevation of the head of the illustrative machine; Fig. 8 is a view, looking in the direction of the arrow 8 in Fig. 9, of a thread lifter mechanism of the illustrative machine; Fig. 9 is a view of the thread lifter

mechanism looking in the direction of the arrow 9 in Fig. 7; Fig. 10 is a front elevation of the head of the illustrative machine; Fig. 11 is a front elevation of the shuttle device of the illustrative machine; Fig. 12 is a left hand side elevation, partly in section, of the shuttle device shown in Fig. 11; Fig. 13 is a side elevation of the shuttle casing of the shuttle device when viewed in the direction of the arrow 13 in Fig. 11; Fig. 14 is another view of the said shuttle casing when viewed in the direction of the arrow 14 in Fig. 11; Fig. 15 is a front elevation of the bobbin case of the illustrative machine; Fig. 16 is a view of the said bobbin case when viewed in the direction of the arrow 16 in Fig. 15; Fig. 17 is a sectional view of the bobbin case on the line 17—17 in Fig. 16; Fig. 18 is a rear view of the said bobbin case; Fig. 19 is a sectional view of the bobbin case on the line 19—19 in Fig. 15; Fig. 20 is a side elevation, partly in section, of driving mechanism of the illustrative machine for the said shuttle device; Fig. 21 is an end elevation of parts of the mechanism shown in Fig. 20; Fig. 22 is a right hand side elevation of part of a needle thread measuring mechanism of the illustrative machine in the head of the machine; Fig. 23 is an inverted plan view, partly in section, of the mechanism shown in Fig. 22; Figs. 24 and 25 are diagrammatic views of some of the parts shown in Fig. 22 in different relative positions; Fig. 26 is a side elevation of other parts of the said needle thread measuring mechanism situated in the column of the machine; Fig. 27 is a right hand side elevation, partly in section, of a lower portion of the illustrative machine illustrating part of the needle thread measuring mechanism and thread lock actuating mechanism of the machine; Fig. 28 is a front elevation of part of the whirl driving mechanism of the illustrative machine; Fig. 29 is a front elevation of the needle thread paying-off mechanism of the illustrative machine; Fig. 30 is a sectional side elevation of an oil filter of the illustrative machine; Fig. 31 is a diagram illustrating the relative timing of various parts of the illustrative machine; Fig. 32 is a right hand side elevation, partly in section, of the clutch mechanism and two speed driving mechanism of the illustrative machine; Fig. 33 is an elevation of a roller clutch of said clutch mechanism; Fig. 34 is an elevation, partly in section, of some of the parts of the clutch mechanism when viewed from the right in Fig. 32; Fig. 35 is a sectional plan view of the spring plunger and its associated parts shown in Fig. 32; Fig. 36 is a face view of the parts shown in Fig. 35, looking from the right; Fig. 37 is a front elevation of an alternative take-up device and thread locking arrangement for the illustrative machine; Fig. 38 is a diagram illustrating the relative timing of the said alternative take-up device and thread lock arrangement; and Fig. 39 is a detail view of the hand lever and latch shown in Fig. 5.

The illustrative machine comprises a column 1 on the upper end of which is secured a head 3 which supports various stitch forming and work feeding mechanisms of the machine.

The machine may be driven by means of an electric motor 5 enclosed in the lower portion of the column or by a belt from a line shaft which passes around fast and loose pulleys on a driving shaft 7 of the machine. The driving shaft 7 has rotatably mounted on its rear end a double grooved pulley 9 which is connected by

two belts 11 to a double grooved pulley on the motor. The driving shaft has mounted on it between the pulley 9 and its forward end a clutch and a two speed driving mechanism of the kind described in the specification of United States Letters Patent No. 2,138,403.

The column has secured to the front of it a bracket 13 on which is rotatably mounted, on a vertical axis, a shoe entering horn 15 in the upper end of which is rotatably mounted a needle threading whirl. The forward end of the driving shaft has rotatably mounted on it a bevel wheel 17 (Fig. 32) which meshes with a bevel wheel 19 secured on the lower end of a vertical shaft 21 extending upwardly through the column and into the head. Secured on a vertical shaft 23 (Fig. 3) above and splined to the shaft 21, is a bevel gear 25 which meshes with a bevel gear 27 secured on the left hand end of a horizontal crank shaft 29 extending laterally of the machine and rotatably mounted in the head 3. When viewed from the front of the machine the driving shaft is at the left of the axis about which the horn rotates and a take-up actuating shaft 31 (Figs. 2 and 4) is rotatably mounted in the column in front of and axially in line with the driving shaft 7. The take-up actuating shaft 31 is driven in the opposite direction to the driving shaft 7 by the aforesaid bevel gear 19 on the lower end of the vertical shaft 21 which meshes with a bevel gear 33 on the rear end of the take-up actuating shaft 31.

Rotatably mounted in the column at a somewhat higher level than the driving shaft and a little at the left of a forwardly and rearwardly extending vertical plane through the extended axis about which the horn rotates is a horizontal forwardly and rearwardly extending thread-lock shaft 35 which actuates thread locks and a thread measure of the machine. The thread-lock shaft is driven by a spur gear 37 on the take-up shaft 31 which meshes with an idler gear 39 rotatably mounted on a stud secured in the column and a spur gear 41 on the thread lock shaft which meshes with the idler gear 39. The take-up shaft 31 and thread lock shaft 35 therefore rotate in the same direction. The thread-lock shaft 35 has secured to it near its forward end a bevel wheel 43 which is connected by means hereinafter described to the aforesaid whirl to drive the latter in an anti-clockwise direction when viewed from above.

The various shafts above referred to are all driven at the same speed. A hooked needle 45 (Figs. 5 and 6) of the illustrative machine has a lower curved work penetrating portion, the radius of the curve of the centre line of this portion of the needle being about five inches. The upper and straight end portion of the needle is clamped in the forward end of an arm 47 of a needle bell-crank lever 49 (which extends forwardly from the pivot portion of the lever) by an eye bolt 51 through which the upper end portion of the needle passes and which clamps one side of the stem of the needle in a V-groove extending upwardly along a forward face 53 on the arm 47 of the bell-crank lever. The lower portion of the needle is circular in cross-section and the stem is square, two faces of the square stem being clamped against the sides of the V-groove in the arm. The needle is therefore positioned on the arm and prevented from twisting by the squared stem and V-groove. The face 53 on the arm 47 in which is formed the V-groove is inclined rearwardly and towards the right and

the eyebolt extends at right angles to this face towards the left hand side of the arm against which a nut on the bolt engages.

An awl 55 (Figs. 6 and 7) of the illustrative machine is secured in the forward end of a rearwardly extending arm 57 of an awl bell-crank lever 59 lying just at the right of the arm 47 of the needle bell-crank lever. The lower portion of the awl is circular in cross-section and the radius of the centre line of this portion is about five inches, the awl and needle swinging upwardly and downwardly towards the aforesaid work entering horn about the same axis, as will hereinafter appear. The upper portion or stem of the awl is curved similarly to the lower portion but is square in cross-section. The stem of the awl is clamped, similarly to the needle, by an eyebolt 61 in a groove formed in a face 63 on the forward end of the arm 57 of the awl bell-crank lever, which face extends rearwardly and to the left from the forward end of the arm. The lower portion of the awl is offset towards the left from the stem of the awl, i. e. it is nearer to the needle than the stem and this offset of the lower portion of the awl to its stem and the arrangement of the inclined faces against which the needle and awl are secured enables their lower portions to be positioned comparatively close together.

The needle and awl bell-crank levers are pivoted, for movement about a common horizontal axis 65 (Fig. 7) to a feed bracket 67 (Fig. 6) which is pivoted on a vertical stud 69 secured in the machine head rearward of the pivotal connection of the needle and awl bell-crank levers to the bracket and slightly to the right of the vertical plane in which the vertical axis of the shoe entering horn lies.

The needle-bell-crank lever 49 has extending towards the left from its hub a sleeve 71 (Fig. 6) which is rotatably mounted in a bearing on the aforesaid feed bracket 67. The sleeve 71 is reduced in external diameter along its left hand end portion, which is within the bearing, and the reduced portion has threaded on it a collar 73 on the outer end of which is formed a flange 75 the inner face of which engages the left hand end of the bearing. The inner end of the collar is forced against the shoulder formed by the reduced portion of the sleeve 71 on the bell-crank lever by screwing it on to the sleeve 71 and the latter is therefore prevented from moving laterally by reason of the engagement of the lever with the right hand end of the bearing and the flange 75 on the collar 73 with the left hand end of the bearing. The collar 73 has an inwardly extending circular face 77 between which and the left hand end of the sleeve 71 on the needle bell-crank lever is a small space in which can rotate a flange on a nut 79. The nut 79 has threaded engagement with the threaded left hand end portion of a spindle 81 which passes through and is rotatably mounted in the sleeve 71 and hub of the needle bell-crank lever 49. The aforesaid collar 73 which is threaded on the reduced end portion of the sleeve 71 on the needle bell-crank lever has extending to the left from the flange 75 on its outer end an externally threaded sleeve portion 83 on which is secured by a nut 85 a forwardly extending arm 87, clamped against the flange 75 by the nut 85. The arm 87 is secured at its forward end to the left hand side of the needle carrying arm 47 near its forward end and affords support to the latter arm against undesired lateral movement. If the aforesaid nut 79, which

has extending to the left a portion by which it may be rotated, on the spindle 81, is rotated the spindle is adjusted lengthwise in the sleeve 71 on the needle bell-crank lever and the awl bell-crank lever 59 which is secured on the spindle is thereby adjusted towards or from the needle bell-crank lever 49 to adjust the awl relatively to the needle. The nut 79 is secured in adjusted position on the spindle by a locknut 89 threaded on the left hand end of the spindle.

The spindle 81 passes through the awl bell-crank lever 59, which is secured to it and which lies just to the right of the needle bell-crank lever 49, and its right hand end portion is rotatably mounted in a second bearing on the aforesaid feed bracket 67. Secured on the right hand end of the spindle 81 is a forwardly extending arm 91 the forward end of which is secured to the right hand side of the forward end portion of the arm 57 of the awl bell-crank lever 59. The forwardly extending arm 91 provides support to the forward end of the awl carrying arm 57 and prevents undesired lateral springing movement of the latter. The aforesaid feed bracket 67 is supported against up or down movement by faces 93 (Figs. 5, 6 and 7) on the machine head which engage the upper and lower faces of lugs 94 on the bracket but allow the bracket to swing about the aforesaid pin on which it is pivoted.

The feed bracket 67 has extending to the left from it an arm 95 (Fig. 6) in the left hand end of which is a curved slot 97. Adjustably secured in the latter slot is a vertical stud 99 on which is pivoted the forward end of a rearwardly extending horizontal link 101. The rear end of the link 101 is pivotally connected by a vertical stud 103 to one arm 105 of a horizontal bell-crank lever 107. The bell-crank lever 107 is pivoted on a vertical pin 109 secured in the machine head and has a second rearwardly extending arm 111 having mounted on it a cam roll 113 which enters a cam groove in a cam 115 secured on the aforesaid vertical shaft 23. As the vertical shaft 23 rotates the cam 115 causes, through the bell-crank lever 107 and link 101, the feed bracket 67 to oscillate about the vertical pin 69 on which it is pivoted to feed the work by means of the awl when the latter has been moved downwardly into engagement therewith. By adjusting the forward end of the link 101 along the curved slot 97 in the arm 95 on the feed bracket 67 the length of feed movement may be adjusted. It will be understood that the awl and needle move together laterally during feed and return movements of the awl. When the awl and needle are at the right hand end of their movement the needle is above the usual opening in the top of the horn and when the awl and needle are in this position the curved slot 97 in the arm 95 on the feed bracket is concentric to the pivot 103 of the rear end of the link. Adjustment of the forward end of the link 101 along the slot 97 does not therefore affect the position of the needle relatively to the horn at this end of its movement. When the awl and needle are at the left hand end of their movement the awl requires to be above the opening in the top of the horn so as to bring the hole made by it in the work beneath the needle when the latter is in its right hand position. If the awl has been so positioned relatively to the needle that when it is at the left hand end of its movement it is above the opening in the horn and an adjustment of feed length is made by adjusting the forward end of the link 101 along the curved slot 97, an adjustment is also necessary.

of the awl relatively to the needle. In other words the awl and needle must always be one stitch length apart and this is effected by adjusting the awl relatively to the needle, by the means hereinbefore described, when the length of feed is adjusted.

The up and down movements of the needle 45 are effected by connections between the needle-bell-crank lever 49 and a crank 131 on the aforementioned crank shaft 29. These connections comprise a short link 119 (Fig. 5) pivotally connected at its forward end by a ball joint to a second upwardly and rearwardly extending arm 121 of the needle bell-crank lever 49. The rear end of the short link 119 is pivotally connected by a ball joint to the lower end of a depending arm 123 which is pivoted on a horizontal shaft 125 extending laterally of the head of the machine and secured therein. The short link 119 is positioned more or less above the vertical pin 69 about which the aforesaid feed bracket 67 swings so that during lateral movement of the needle bell-crank lever little movement of the ball joints takes place. The depending arm 123 also has pivoted to its lower end a second and longer link 127 which extends downwardly and rearwardly and at its lower end is pivotally connected to the forward end of a pitman 129 which extends more or less horizontally rearwardly from its forward end. The rear end of the pitman 129 is pivotally mounted on the aforementioned crank 131 on the crank shaft 29. About midway between its ends the pitman 129 is pivoted to the lower end of a radius arm 133 which at its upper end is pivoted on a horizontal shaft 135 which is rotatable in the machine head. The axes of the various pivotal connections between the needle bell-crank lever 49 and the crank 131 all extend laterally of the machine. As the crank 131 rotates the forward end of the pitman 129 moves in a closed path of such a shape that the needle is moved upwardly and downwardly and is caused to dwell at the top and bottom of its movement for purposes which will hereinafter appear.

The up and down movements of the awl 55 are also effected by connections between the aforesaid awl bell-crank lever 59 and a crank 137 on the crank shaft 29 which is at the right of the needle actuating crank 131. The connections between the awl bell-crank lever 59 and the crank 137 comprise a short forwardly and upwardly extending link 139 (Fig. 7) connected by ball joints to a rearwardly extending arm 141 of the awl bell-crank lever 59 and to the lower end of an arm 143 which is secured at its upper end to a horizontal shaft 145 rotatably mounted in the machine head. The shaft 145 has secured on it a second arm 147 which extends downwardly and rearwardly and has pivotally connected to its lower end the rear end of a second and longer link 149. The forward end of the link 149 is pivotally connected to the forward end of a pitman 151 the rear end of which is pivoted on the awl actuating crank 137. The pitman 151 about midway of its length is pivotally connected to the lower end of a radius arm 153 the upper end of which is pivoted on the same shaft 135 as the aforementioned radius arm 133 which is pivoted to the needle actuating pitman 129. As the awl crank 137 rotates the forward end of the pitman 151 moves in a closed path and causes, through its connections to the awl bell-crank lever 59, the awl to move upwardly and downwardly and to dwell at appropriate times in the machine cycle. The awl during its downward movement nearly

pierces the work and when the work has been fed the awl may be moved down to penetrate the work before it is moved upwardly out of the work.

5 The illustrative machine has a thread lifter or loop spreader 155 which engages one leg of the loop of thread, i. e. that leg which extends downwardly into the work supporting horn, and moves forwardly and upwardly to spread the loop so that a shuttle beak, hereinafter described, can readily enter the loop. The thread lifter has at its lower end a hook arranged to swing, forwardly and upwardly from a position rearward and slightly to the left of the needle, just under the 10 needle point as the needle is rising with the loop of needle thread in its hook to engage the thread and spread the loop forwardly and upwardly. The thread lifter 155 (Figs. 7, 8, 9 and 10) 15 extends upwardly from its hooked lower end and is secured in a lever 157 by a screw 159. The lever 157 is pivoted on a spindle 161 which is secured in a bracket 163 secured on the head of the machine. The spindle 161 when viewed from the front of the machine, extends upwardly and 20 towards the right at an angle of about fifty degrees to a horizontal plane below the spindle and the spindle 161, when viewed from the right hand side of the machine, extends upwardly and rearwardly at an angle of about sixty degrees to 25 said plane. The angular disposition of the spindle 161 causes the hooked lower end of the thread lifter to move as it is swung forwardly and upwardly about the axis of the spindle 161 in a curved path when viewed from above from a position rearward and slightly to the left of the 30 needle towards the right and then towards the left to a position in front of and slightly to the left of the needle path. The barb of the needle is positioned about twenty degrees round to the right from the front of the needle and the movement of the lower hooked end of the thread lifter from its position at the rear and left of the needle towards the right as it swings forwardly 35 moves at this time in a path substantially at right angles to the needle barb and therefore in a very favorable direction for engaging the length of thread extending from the needle into the horn. Further movement of the thread engaging end of the thread lifter towards the right 40 after it engages the thread carries the thread lifter well out of the path of the shuttle beak as the latter is rising to engage, later, that length of thread and the subsequent movement of thread engaging end of the thread lifter towards the left during its continued forward movement 45 places the length of thread extending from the needle to the thread lifter in a favorable position to be engaged by the shuttle beak, rearward of its tip, after the thread lifter has reached its most forward position.

50 The lever 151 has pivotally connected to it the forward end of a rearwardly extending rod 165. The rod 165 at its rear end is pivotally connected to the end of an arm 167 of a bell-crank lever 55 169 which is pivoted on a shaft 171, secured in the machine head, parallel to the spindle 161. Another arm 173 of the bell-crank lever 169 carries a cam roll 175 which engages in a cam groove 177 formed in a cam 179 secured on the crank shaft 29 of the machine by which the thread lifter is actuated.

55 At the left of the needle 45 is a rotary shuttle which is rotated once during each cycle of the machine. The shuttle (see Figs. 11 to 19) comprises a rotary shuttle casing 181 and a bobbin

case 183 in the shuttle casing. The shuttle casing 181 is of a similar nature to that described in U. S. Patents No. 2,000,254 and No. 2,049,369, being formed in two parts secured together and having formed between them an undercut guideway 185 which receives the shuttle raceway comprising a flanged guide formed on a ring 187 normally held against rotary movement and partly surrounding the shuttle casing 181, the flanged guide being formed on the inside of the ring. The ring 187 is supported in a guideway formed partly in a bracket 189 secured on the front of the machine head and partly in a coverplate 191 secured to the front of the bracket 189. The lower portion of the ring 187 is cut away to allow the shuttle casing 181 to carry a loop of needle thread over the bobbin case 183. The ring 187 is normally held against rotation in its guideway by a spring plunger 193 in the bracket 189, the forward end of which engages in a recess formed in the rear face of the ring 187 so that, for a purpose hereinafter described, the ring may rotate in its guideway. The lower portions of the bracket 189 and the cover plate 191 are both cut away to allow the shuttle casing 181 to take a loop of needle thread from the needle and thread lifter and pass it over the bobbin case.

The shuttle casing 181 has formed on it a pronged, i. e. forked beak or hook 195, part of which is formed on each part of the shuttle casing so that the undercut guideway 185 which receives the shuttle raceway passes through the nose or end portion of the beak or hook which is chisel shaped or blunt rather than pointed. The thread engaging face 197 of the beak is comparatively wide at its outer end and widens further towards the body of the shuttle casing. When the beak engages the loop of needle thread held open by the needle and thread lifter the thread engaging face 197 of the beak extends upwardly and rearwardly at an angle of about twenty degrees to the horizontal, and is parallel to the length of needle thread then extending forwardly from the needle to the thread lifter. The side edges of the beak at its root are well rounded so that the thread can freely slide across the face of the beak if necessary. The shuttle beak has at the rear of it a cam 199 which as the beak takes the loop of thread from the needle thrusts the thread rearwardly out of the hook of the needle. The bobbin case 183 is rotatably mounted on a pin extending forwardly from the rear wall of a cylindrical recess in the shuttle casing 181 which receives the bobbin case, which is concentric to the axis of rotation of the shuttle casing. The bobbin case 183 has on its front face a groove 201 (Figs. 15 and 19) extending radially of the bobbin case. To prevent the bobbin case from rotating completely but to allow it to oscillate slightly the groove 201 is engaged by the rounded end of a stud 203 secured in the lower end of an arm 205 (Figs. 11 and 12) which extends downwardly in front of the bobbin case. The arm 205 is secured on a horizontal shaft 207 extending laterally of the machine. The shaft 207 is rotatably mounted in bearings formed on the aforesaid cover-plate 191, between which bearings the arm is positioned. The arm 205 has extending rearwardly through it a screw 209 the rear end of which engages the front face of the aforesaid cover-plate 191 and the screw 209 may be adjusted so as to position the stud 203 so far forwardly in relation to the groove 201 in the bobbin case as to just allow the thread to pass freely between the stud and the bobbin case

as a loop of thread is passing over the bobbin case. The shaft 207 may be rotated to swing the arm 205 upwardly from in front of the bobbin case so that the latter may be removed for the insertion of a fresh bobbin of thread therein by mechanism similar to that described in U. S. Patent No. 1,991,456, including a hand lever 211.

The bobbin case 183 has extending downwardly from it a nose 213 through which the shuttle thread passes and from the lower end of which the shuttle thread extends to the work. The lower end of the nose is positioned so far from the axis of the shuttle casing 181 and bobbin case 183 that the thread issuing from the end of the nose is beyond the path of movement of the tip of the shuttle beak 195 so that there is little if any likelihood of the beak engaging the shuttle thread as it rotates. The shuttle thread passes from a bobbin in the bobbin case through an opening 215 (Fig. 16) in the periphery of the bobbin case and through a tension device on said periphery to a groove 217 extending partly around the bobbin case and partly along one side of the nose and from the groove through a hole, in the outer end of the nose, which passes upwardly for a short distance along the nose and connects with the groove.

The tension device comprises a small slide 219 which extends laterally of the bobbin case and presses the thread against the forward face of the groove 217 on the bobbin case to apply tension to the thread. The slide 219 is guided in a dovetailed guideway formed in the bobbin case. The slide has formed at one end of it a recess which is engaged by one end of a spring member 221 which presses the slide against the thread. The bent ends of the spring member enter holes 223 in the bobbin case and as shown in Fig. 17 a number of these holes are provided in the bobbin case so that springs of different length may be used and different tensions applied to the thread as is found to be desirable.

The shuttle casing 181 is driven by a driving member 225 extending forwardly from the forward end of a shuttle driving shaft 227 (Figs. 3, 20 and 21) which is rotatably mounted in the machine head and which from its forward end extends upwardly at an angle of about 15° to the horizontal and to the left at an angle of about 5° to a vertical plane at right angles to the crank shaft 29. The driving member engages the aforesaid thread engaging face 197 of the beak and a face 229 on the casing spaced away from the latter face around the casing 181, there being sufficient space between the member 225 and the two faces 197, 229 to allow the needle thread to pass between them as the loop of needle thread is passed over the casing 181. The shuttle driving shaft 227 has at its rear end a crank pin 231 which is connected by a link 233 to a crank pin 235 on the forward end of a second shaft 237 the axis of which is parallel to but offset from the axis of the shuttle driving shaft 227. The shaft 237 is driven at a uniform speed by a spiral gear 239 on its rear end and a spiral gear 241 on the aforesaid vertical shaft 23 with which it meshes and the crank and link arrangement between the shaft 237 and the shuttle driving shaft 227 causes the speed of the latter shaft and shuttle casing to vary during their rotation in such a manner that the speed of the shuttle casing is increased while the loop of needle thread is being passed over the bobbin case and is decreased during the time the needle is drawing the loop of thread passed over the bobbin case down to the work and while the

thread lifter is opening the next loop, i.e. a little before the beak of the shuttle casing takes the loop from the needle and thread lifter. The driving member 225 for the shuttle casing and the crank and link arrangement are substantially similar to those described in U. S. Patent No. 1,991,456.

The upward inclination of the shuttle driving shaft 227 enables the beak 195 to engage the length of the needle thread extending from the thread lifter to the needle close to the needle and to lift the loop of thread drawn up by the needle and pass it over the bobbin case without the rear limb of the loop engaging the needle which at this time is more or less in its fully raised position. The lateral inclination of the shuttle driving shaft enables the aforesaid cranks which drive the needle and awl to be conveniently positioned in the machine at the rear of the needle and awl.

If a loop of needle thread should, when the shuttle beak is taking a loop from the needle and thread lifter, become hooked over only one prong of the beak 195 the thread will, as the shuttle casing rotates, become jammed between the shuttle casing 181 and the aforesaid ring 187 on which the flanged guide on which the shuttle casing rotates is formed. After the thread becomes so jammed the ring 187, which as hereinbefore described is normally held stationary by the spring plunger 193 aforesaid, rotates with the shuttle casing until the machine is stopped. As the shuttle casing and ring rotate together the needle thread is severed between the end portion of the ring, the edges of which are sharpened, and a shear plate 243 (Fig. 11) formed on the bracket and a shear plate formed on the cover plate, the plates 243 being formed on the bracket and cover plate at the right hand end of the aforesaid opening in their lower portions and being so shaped as to conform closely to the outer portion of the ring. After the machine has been stopped the shuttle casing 181 is turned backward, by reversing the rotation of the vertical shaft 23 which has on its upper end a hand wheel 245 (Fig. 1) for rotating it by hand, and during such backward movement of the shuttle casing the ring 187 turns with it until the recess in the rear of the ring engages with the plunger 189 whereupon the shuttle casing rotates relatively to the ring until the piece of thread is freed from them and either falls or may be pulled away. The recess in the back of the ring and the plunger 187 each have a square and bevelled edge, the bevelled edges being arranged to allow the ring to move relatively to the plunger when thread jams between the shuttle casing and the ring and the square edges being arranged to arrest and position the ring when the casing and ring are turned in the reverse direction.

The arrangement whereby the ring 187 is able to rotate if the thread becomes jammed between the ring and the shuttle casing enables the latter to be driven positively which is desirable since, as will hereinafter appear, the beak 195 on the shuttle casing 181, sets the stitches against a thread lock and therefore if the shuttle casing were yieldingly driven the yielding device would have to be strong enough not to yield during the stitch setting and might be too strong to yield readily enough if the thread jams as aforesaid with the result that damage might be caused to the machine.

In the illustrative machine the axis of the bobbin case 183 is offset from the axis of the shuttle

casing 181 in such a manner that the bobbin case rises and falls during the rotation of the shuttle casing and as it rises pulls off shuttle thread from the bobbin in the bobbin case and as it falls slackens the shuttle thread extending from the bobbin case to the work so that during the pulling down of the upstanding loop of the previous stitch by the needle and the setting of the stitch the shuttle thread, which has been fully paid off just before the stitch is set, can readily be pulled down against the upper face of the work and into the work.

The axis of the bobbin case is offset three thirty-seconds of an inch from the axis of the shuttle casing so that three sixteenths of an inch of thread is pulled from the bobbin each time the bobbin case rises. The axis of the bobbin case lies in a radial plane, in which the axis of the shuttle casing lies, which is spaced about 60° behind, considered in the direction of rotation of the shuttle casing, another radial plane in which the axis of the shuttle casing and the tip of the beak lie. With this arrangement the length of shuttle thread extending from the bobbin case to the work has been fully slackened when the needle has pulled the upstanding loop of needle thread of the previous stitch down to the work and it may be slightly into the work, that is, during that time in which the shuttle thread is laid along the work and it may be pulled slightly into the work with the loop of needle thread. The shuttle thread therefore offers no resistance to the pulling down of the previous loop by the needle and undesirable relative reeving of the needle and shuttle threads is avoided.

The illustrative machine has a presser foot 247 for holding the work against the horn at all times in the cycle of the machine except when the work is being fed and the presser foot is automatically raised from the work after the stitch forming and work feeding devices stop. The presser foot 247 is raised and lowered and locked in its lowered position by mechanism generally similar to that described in U. S. Patent No. 2,054,078, but presenting certain advantages thereover.

The presser foot 247 is positioned just at the right of the awl and is supported on the lower end of presser foot bar 249 and its lower end is shaped to enter conveniently a stitch receiving channel in the sole of a shoe supported, sole uppermost, on the horn. The presser bar 249 (Figs. 1 and 7) is supported by the forward ends of two parallel substantially horizontal arms 251, 253, one above the other, the rear ends of which are secured on horizontal shafts 255, 257 extending laterally of the machine which are rotatably mounted in the machine head. The lower arm 251 is pivotally connected to the presser bar 249 a little below the middle of the bar and the upper arm 253 is pivotally connected to the bar at its upper end. The presser bar 249 therefore moves substantially vertically upwardly and downwardly having only a very slight forward and rearward movement due to the swinging of the arms.

The shaft 257 on which the upper presser bar arm 253 is secured also has secured on it a downwardly extending arm 259 the lower end of which is pivotally connected to the forward end of a rearwardly extending link 261 the rear end of which is pivotally connected by a horizontal pin 263 extending laterally of the machine to the middle portion of a pair of parallel more or less vertical short links 265. The lower ends of the short links 265 are pivotally connected by a horizontal pin 267 which extends laterally of the ma-

chine to the forward end of a rearwardly extending rod 269 between the links. The rear end of the rod 269 is pivoted on a horizontal stud 271 extending laterally of the machine which is secured in a curved slot 273 formed in an upwardly extending arm 275 which is secured to the aforesaid shaft 135 on which the aforesaid radius arms 123, 153 associated with the needle and awl driving mechanisms are pivoted. Also secured on the shaft 135 is a rearwardly extending arm 277 which has on its rear end a cam roll 279 engaging in a cam groove formed in one face of a cam on the crank shaft 29 of the machine. The curved slot 273 in the arm 275 is substantially concentric to the pivot of the forward end of the rod 269 when the presser foot is down on the work of average thickness. The cam and connections therefrom cause the presser foot 247 to be raised from the work while the latter is being fed and the stud 271 may be adjusted in the curved slot 273 to adjust the amount of lift of the presser foot by the cam. The upper ends of the aforesaid short links 265 are pivotally connected by a horizontal pin 281 extending laterally of the machine to a horizontal rearwardly extending stirrup 283 (Fig. 23). The pin 281 which connects the short links 265 to the stirrup 283 passes through openings slightly larger than the pin in a horizontal central wedge member 285 and a pair of horizontal wedge plates 287 which extend forwardly from the pin. The central wedge member 285 and wedge plates 287 are slidably mounted in a bracket 289 secured on the machine head and have associated with them a roller-locking arrangement similar to that described in said U. S. Patent No. 2,054,078. One end of a row of rollers 291 of the locking arrangement is supported against endwise movement by an adjustable bar 293 which is adjustably mounted in the said bracket. The other end of the row of rollers 291 is actuated, to lock the presser foot by a presser foot locking finger 295. The presser foot locking finger 295 is secured on a horizontal shaft 297 (Figs. 7 and 22) extending laterally of the machine and rotatably mounted in the said bracket 289 above the rollers and wedge members. An upwardly extending arm 299 is also secured to the said shaft 297 and its upper end is pivotally connected to the forward end of a rearwardly and downwardly extending rod 301. The rear end of the rod 301 is pivotally connected to the upper end of one arm 303 of a bell-crank lever which is pivoted on a horizontal shaft 305 extending laterally of the machine and secured in the machine head. The other arm 307 of the latter bell-crank lever extends downwardly and rearwardly from the shaft and has at its lower end a cam roll 309 which engages in a cam groove formed in one face of a cam on the aforesaid crank shaft 29 of the machine. The upper end of the aforesaid arm which is secured on the shaft to which the finger is secured is connected to the forward end of the rod by a yielding connection. The upper end of the arm 299 has secured in it a pin 311 which passes through a slot in a sleeve 313 secured on the forward end of the rod 301. A compression spring 315 in the sleeve 313 engages the forward side of a block 317 slidably mounted in the sleeve, in which block the pin is secured and an adjustable screw 319 in the forward end of the sleeve 313. When the rod 301 is moved forwardly by its cam lever the finger 295 is moved positively to unlock the presser foot and when the rod is moved rearwardly the finger is

yieldingly actuated to lock the presser foot. The spring 315 allows the finger to be moved in a direction, by means hereinafter described, to unlock the presser foot at a time when the latter is locked by the action of the cam which acts on the cam roll 309.

A feature of the invention consists in the provision of power actuated mechanism which is controlled by the movements of the stirrup 283 acting through a mechanical relay device to adjust the operation of the thread measuring pull-off of the machine to measure the required amount of new thread from the supply for the next stitch in accordance with the thickness of the work. To this end the rear end of the aforesaid stirrup 283 has pivotally connected to it by horizontal pins 321 extending laterally of the machine a pair of parallel links 323 the rear ends of which are pivoted on horizontal coaxial studs 325 extending laterally of the machine and projecting outwardly from a pair of parallel triangular levers 327, at one corner thereof. Another corner of the pair of triangular levers which is nearer the front of the machine than the first mentioned corner but in about the same horizontal plane has pivotally connected to it at 329 the forward end of a rearwardly extending rod 331, lying between the triangular levers 327 and also between the aforesaid parallel links 323, the rear end of which rod 331 is pivotally connected to the upper end of one arm 333 (Fig. 7) of a lever which is secured on a horizontal shaft 335 extending laterally of and rotatably mounted in the machine head above and a little to the rear of the aforesaid crank shaft 29. Another arm 337 of the latter lever extends downwardly and rearwardly and has pivotally connected to it the upper end of a downwardly extending rod 339 the lower end of which is pivotally connected to thread measuring mechanism of the machine hereinafter described. The arm 337 has formed in its rear end a slot 341 in which is adjustably secured a stud 340 on which the upper end of the downwardly extending rod 339 is pivoted. The third corner of the aforesaid pair of triangular levers 327 which is higher than the two other corners is pivotally connected, at 342, to and within a bifurcated bracket 343 from which extend laterally outwardly horizontal trunnions 345 rotatably mounted in the machine head and lying in the same horizontal plane as the axis of the pivot pins 321 at the rear end of the aforesaid stirrup 283. The left hand trunnion has secured on it an upwardly and rearwardly extending curved arm 347 (Fig. 7) the upper end of which has pivotally connected to it the upper end of a downwardly extending link 349 the lower end of which is pivotally connected to the forward end of the aforesaid pitman 151 of the awl actuating mechanism. During each cycle of the machine the bifurcated bracket 343 is swung upwardly and downwardly, by its connection to the pitman, about the axis of the trunnions 345, assuming that the presser is resting on the work, the bifurcated bracket is swung fully upwardly the pivot 342 connecting one corner of the triangular levers 327 to the bifurcated bracket 343 is higher than the other two corners and the axes of the pivots 325, 329 at the other two corners of the triangular levers 327 lie substantially in the horizontal plane aforesaid in which the axis of the pivot pins 321 in the aforesaid stirrup and the axes of the trunnions 345 on the bifurcated bracket 343 lie. The parallel links 323

and the aforesaid rod 331 also lie in the same horizontal plane or substantially so and if the presser foot is raised or lowered the arm 333 connected to the measuring mechanism is swung forwardly or rearwardly. In Figs. 7 and 22 the bifurcated bracket 343 is shown at the top of its path of movement but since the parts are shown in the stopping position of the machine at which time the presser has been raised from the work the axes of the pivots 329 and rod 331 are shown as being somewhat out of said plane. When the bifurcated bracket 343 is swung fully downwardly the axes of the pivots 342 lie in the said horizontal plane at the rear of the pivots 345 of the bifurcated bracket, and the links 323 extend downwardly and rearwardly from the stirrup 283. The aforesaid rod 331 and the sides of the triangular levers 327 which extend from the pivots 342 to the pivot 329 lie side by side. If the presser foot is moved upwardly or downwardly while the parts are in this position the triangular levers 327 and the forward end of the rod 331 are swung upwardly or downwardly about the pivots 342 but since the axes of the pivots 342 of the levers and rod 331 lie substantially in the same plane little or no endwise movement of the rod takes place and there is therefore little or no movement of the lever connected to the measuring mechanism.

When the presser foot is in one particular heightwise position, i. e. when the presser foot is resting on work of a medium thickness, the axes of the pins 321 and pivot 329 are coincident with the axis of the trunnions 345 on the bifurcated bracket 343 and upward and downward movement of the latter bracket does not move the arm 333 which is connected to the thread measuring mechanism forwardly or rearwardly. When the presser foot is resting on work which is thinner or thicker than the said medium thickness the axis of the pins 321 at the rear of the stirrup member lies forwardly or rearwardly of the axis of the trunnions 345 and upward and downward movement of the bifurcated bracket moves the arm 333 connected to the thread measuring mechanism forwardly and rearwardly, see Figs. 24 and 25. At the time in the machine cycle when the presser foot moves downwardly on to the work to press the work against the horn the bifurcated bracket 343 is substantially in its lowest position and the axis of the pins 321 at the rear end of the stirrup 283 is positioned thereby forwardly or rearwardly relatively to the axis of the trunnions 345 on the bifurcated bracket and as the bifurcated bracket 343 is swung upwardly the arm 333 connected to the measuring mechanism is swung forwardly or rearwardly a distance depending upon the offset position of the axis of the pins 321 at the rear of the stirrup relatively to the axis of the trunnions 345 on the bifurcated bracket and thus sets the measuring mechanism to cause the latter to subsequently pull off an amount of thread depending upon the thickness of the work. The presser foot 247 is moved downwardly into engagement with the work to press the work against the horn by a spring 351 (Fig. 7), hereinafter described, and it will be apparent that the only duty imposed on this spring besides moving the presser foot downwardly is that of moving the parallel links 323 and the rod 331 and that thereafter power-operated mechanism operates the thread measure controlling mechanism. A comparatively light spring may therefore be used to move the presser foot into engagement with the

work. It is usually desired that the thread locks shall all be set a uniform distance in the work from the upper surface of the work and the thread measuring mechanism is so adjusted by 5 the heightwise position of the presser foot according to the thickness of the work that the amount of thread measured off for each stitch is of such a length that the thread locks are all positioned a uniform distance in the work. If 10 the operator tips the work in such a manner that the lower face of the work beneath the presser foot is raised above the horn the heightwise position of the presser foot will not be in accordance with the actual thickness of the work but with 15 the distance of the upper face of the work from the upper face of the horn and the amount of thread measured off will therefore be greater than the thickness of the work calls for with the result that the thread lock is set closer to the 20 upper face of the work than is desired. The amount of thread measured off may be adjusted in proportion to the thickness of the work by adjusting the stud 340 to which the upper end of the aforesaid downwardly extending rod 339 is 25 connected to the measuring mechanism along the slot 341 in aforesaid downwardly and rearwardly extending arm 337 and may be so adjusted that even if the work is tipped as aforesaid the thread lock will be set somewhat within 30 the work.

The forward end of the aforesaid spring 351 which moves the presser foot down onto the work is connected to the lower end of an arm 353 (Fig. 7), secured on the aforesaid shaft 257 on 35 which the upper presser bar arm 253 is secured, which extends downwardly therefrom. The rear end of the spring 351 is connected to a hand lever 355 which is pivoted on a horizontal shaft 357 extending laterally of the machine and secured in the machine head. The hand lever 355 extends upwardly above the top of the head and has pivoted on it a spring pressed pawl arranged to engage a toothed plate 359 secured on the head. The pawl may be released from the teeth 40 and the hand lever may be moved forwardly or rearwardly to adjust the spring and therefore the pressure of the presser foot against the work.

The presser foot may be unlocked and raised by the operator if for any reason the machine 45 is stopped before the end of a cycle, so that work in the machine may be removed, and is unlocked and raised automatically after the stitch forming and work feeding devices have come to rest at the end of a cycle. The aforesaid shaft 297 to which the aforesaid presser foot locking finger 295 is secured has secured to it a depending arm 361 the lower end of which has secured in it a horizontal stud on which is rotatably mounted a cam roll 363. In front of and substantially 50 level with the latter shaft is a transverse shaft 365 rotatably mounted in the head, on which is rotatably mounted a downwardly and rearwardly extending cam arm 367 having formed on its lower end a cam arranged to engage the cam roll 363 on the said depending arm 361.

Extending upwardly from the hub 369 of the cam arm 367 is an upwardly extending arm 371 (Figs. 5 and 7) the upper end of which has extending from it a horizontal pin 373. The pin 373 55 passes through a slot 375 in the forward end of a rearwardly extending rod 377 which is connected to an arm 379 of a bell-crank lever which is secured on a horizontal shaft 381 extending laterally of the machine and rotatably mounted 60 in the rear of the head and which lever and shaft 65

are rotated in an anti-clockwise direction, viewed from the right, after the stitch forming and work feeding devices have come to rest at the end of a cycle and cause the rearwardly extending rod 377 to be moved forwardly. The cam arm 367 has extending upwardly from it a hand lever 383 by which the cam arm may be rotated to unlock and lift the presser foot. When the cam arm 367 is rotated in an anticlockwise direction looked at from the right, by the hand lever 383 or by the aforesaid rearwardly extending rod 377 the cam on the cam arm 367 unlocks the presser foot. The presser foot is thereafter raised, by continued movement of the cam arm in the same direction, by a pin 385, extending laterally from a rearwardly extending projection 387 on the arm 371, arranged beneath a rear arm 389 of a forwardly and rearwardly extending manually adjustable presser lifting lever 391. The presser foot lifting lever 391 is rotatably mounted on an eccentric disc 393 which is secured on the aforesaid transverse shaft 365. A forwardly extending arm of the presser foot lifting lever 391 has in it a laterally extending pin 395 positioned above the arm 353 which is secured on and extends rearwardly from the aforesaid shaft 251 on which the upper arm 253, to which the presser bar 249 is pivoted, is secured. The eccentric disc 393 has extending upwardly from it a handle 397 having in its upper end a spring plunger 399 which is arranged to engage one of a series of notches in a sector 401 secured on the machine head. By adjusting the eccentric disc 393 about the axis of the transverse shaft 365 the distance between the underside of the rear arm 389 of the forwardly and rearwardly extending lever 391 and the pin 385 in the projection 387 may be varied so as to provide more or less lost motion between them and thus vary the distance the presser foot is raised, when the machine stops, to suit the thickness of the work.

The aforesaid cam groove which causes the presser foot to be lifted to allow the work to be fed is so formed that during part of each cycle of the machine the presser foot may be lifted slightly e. g. about one-thirty-second of an inch, against the action of the aforesaid spring 351 which presses it against the work. Such freedom to lift the presser foot this small amount enables the operator to tip the work if this is necessary as it may be when sewing round a shoe. The presser foot is free to be so lifted from about the time when the needle begins to pierce the work until the presser foot is automatically lifted to allow the work to be fed after the needle has drawn a loop of needle thread up through the work.

The aforesaid downwardly extending rod 339, which as aforesaid is connected to thread measuring mechanism of the illustrative machine, is pivotally connected at its lower end to the lower end of a downwardly and rearwardly extending arm 403 (Fig. 26) formed on the left hand end of a horizontal sleeve 405, extending laterally of the machine which is rotatably mounted in the column of the machine at the right of and at about the same heightwise position in the machine as the aforesaid thread lock shaft 35. A horizontal shaft 407 which passes through the sleeve and is adjustably connected thereto so that they rotate together has secured on its left hand end a second downwardly extending arm 409 the lower end of which is pivotally connected to the lower end of an upwardly extending link 411 which is of the same length as the arm 409. The upper end of the link 411 is pivotally con-

nected to a downwardly and forwardly extending link 413 and to an upwardly and rearwardly extending link 415. The lower end of the link 413 is pivotally connected to the rear end of one arm of a forwardly and rearwardly extending thread measuring lever 417. The thread measuring lever 417 is pivoted about midway of its length on a horizontal shaft 419 extending laterally of the machine. The forward end of the 10 arm of the thread measuring lever 417 has on it a thread guiding roll 421 (Fig. 27) around which the needle thread passes. The rear end of the link 415 is pivotally connected to the upper end of an arm 423 which is secured on a horizontal laterally extending shaft 425 rotatably mounted in the column of the machine. The shaft also has secured on it an arm 427 having on its upper end a cam roll 429 which enters a cam groove formed in the peripheral face of a cam 431 on the aforesaid thread-lock shaft 35. The amount of thread measuring movement imparted to the thread measuring lever by the cam is controlled by the position, about its axis, of the lower end of the depending arm 409 on the aforesaid horizontal shaft 407 which passes through the said sleeve 405 and the position of this arm is adjusted by the hereinbefore described mechanism on the head of the machine which is controlled by the presser foot.

If the axis of the pivot connecting the three links 411, 413 and 415 is in alignment with the axis of the horizontal shaft 407 no movement will be imparted to the thread measuring lever by the power operated mechanism on the head controlled by the presser foot and these axes are caused by the cam lever 423, 427 to be in or substantially in this position when the depending arm 403 is adjusted about its axis by the power-operated mechanism on the head controlled by the presser foot so that the thread measuring lever 417 is not moved when the depending arm is positioned by the power-operated mechanism but the amount of thread measuring movement of the thread measuring lever imparted to it by the cam lever 423, 427 is controlled by the position about its axis of the depending arm 403. The depending arm 403 may be adjusted about its axis, independently of its adjustment by the power operated mechanism which is controlled by the presser foot, so as to adjust the amount of thread measured off for a given thickness of work and to determine the position in the work of the thread locks relatively to the upper surface of the work. The shaft 407 which passes through the aforesaid sleeve 405 has secured on its right hand end a downwardly extending indicator arm 433 (Fig. 1) and the shaft has clamped on it, between the indicator arm 433 and the right hand end of the sleeve 405, a collar, which has an arm 435 extending downwardly from it close to the left hand side of the indicating arm 433, which has on its right hand side indicating marks. The collar has formed on its left hand face two oppositely disposed keys which enter recesses formed in the right hand end of the sleeve 405. When the collar is unclamped the shaft may be rotated by means of the indicator arm 433 to adjust the aforesaid depending arm 409 to vary the amount of thread measured off by the thread measuring lever for a given thickness of work. This adjustment of the depending arm 409 and consequent variation of the amount of thread drawn off by the thread measuring lever provides means whereby the depth 75 to which the thread locks are set in the work

may be varied or the length of thread pulled off from the supply may be varied in accordance with the length of the stitches.

The illustrative machine therefore includes mechanism which is set by the heightwise position of the presser foot, power operated mechanism which transfers this setting to other mechanism on the column and further power operated mechanism which actuates the thread measuring lever in accordance with the setting of the latter mechanism.

The aforesaid thread guiding roll 421 on the forward end of the thread measuring lever 411 engages a length of needle thread which extends between upper and lower thread locking devices of the machine hereinafter described.

The thread locking devices are similar and are substantially similar to the thread locking means described in U. S. Patent No. 2,056,670. Each thread locking device (Fig. 4) comprises a thread engaging plate 437, pivoted on an arm of a bracket secured to the column, against which plate the thread is clamped. Each plate 437 has extending from its left hand side a projection 439 having a rounded end which engages in a corresponding shaped recess in the arm of the bracket. Each projection extends horizontally forwardly and rearwardly of the machine and the thread is pressed against the right hand face of each plate. At the right hand side of each thread engaging plate 437 is a clamping plate 441 having extending from its right hand side a screw threaded stem 443, the thread of which is of comparatively coarse pitch. Each stem 443 engages in a rotatable sleeve 445, having a correspondingly threaded axial bore, rotatably mounted in a bore in the bracket on the column to which the aforesaid thread engaging plates are pivoted. The right hand end of each sleeve 445 has secured in it a plug 447 having at its right hand end a rounded end which engages a cylindrical disc 449 in each bore in the bracket. A compression spring 451 in each bore in the bracket engages a disc 449 and also a screw 453 in the right hand end of each bore. The rounded projection on each plug 447 allows each sleeve 445 to be easily rotated. The left hand end of each sleeve 447 is normally pressed by its spring against a face on the bracket and this end of each sleeve has extending laterally from it a comparatively short arm. The short arm of the lower thread lock is shown at 455 (Fig. 27) and the short arm of the upper thread lock at 457. When each sleeve 445 is rotated in one direction its threaded connection with its stem 443 causes the stem and plate to be moved towards the aforesaid thread engaging plate 437 to clamp the needle thread lying between the plates and thereafter during continued rotation of the sleeve 445 the latter moves lengthwise to the right relatively to the stem and further compresses the aforesaid spring. The short arm 455 on the sleeve 445 of the lower thread lock extends upwardly and has pivotally connected to its lower end a rearwardly and upwardly extending rod 461 (Fig. 27) the rear end of which rod is pivotally connected to one arm of a cam lever 463 which is secured on a horizontal shaft 465 extending laterally of the machine and rotatably mounted on the machine column. Another arm of the cam lever 463 has rotatably mounted on it a cam roll 467 which engages a cam groove formed in the aforesaid cam 431 on the thread lock shaft 35. The cam groove causes the lower

thread lock to grip and release the needle thread at appropriate times in each machine cycle.

The short arm 457 of the upper thread lock extends downwardly from its sleeve 445 and the lower end of the arm 457 has pivotally connected to it the forward end of a rearwardly extending rod 469 (Fig. 27). The rear end portion of the rod 469 is pivotally connected to the rear ends of a pair of forwardly extending links 471, one at each side of the rod. The forward ends of the links 471 are pivoted to the upper forked end of a cam lever 473 which is pivoted on a horizontal shaft 475 extending laterally of the machine. The cam lever 473 has on it a cam roll 471 which enters a cam groove in the aforesaid cam 431 on the thread lock shaft 35. The end of the rod 469 rearwardly of the pivot of the links 471 thereto has pivoted to it the upper end of a downwardly extending link 479 the lower end of which is pivotally connected to an arm 481 of a bell-crank lever 483 which is pivoted on a horizontal pivot 485 extending laterally of the machine and secured in the machine column. Another arm 487 of the bell-crank lever 483 has pivotally connected to it the forward end of a rearwardly extending rod 489 of the rear end of which is connected by a pin and slot arrangement to an upwardly extending arm 491 (Fig. 1) of a bell-crank lever 493 which is pivoted on a horizontal stud 495 extending laterally of the machine which is secured in a clutch casing 497 hereinafter referred to. The pin and slot arrangement comprises a slot 499 in the rear end of the rod 489 and a stud 501 which enters the slot and extends laterally from the arm. A spring 503 normally holds the rear end of the slot 499 against the stud 501 and tends to move the rod 489 forwardly. The bell-crank lever 493 is rocked in a clock-wise direction when viewed from the right after the stitch forming and work feeding devices have come to rest. During the operation of the machine the aforesaid pair of links 471 lie parallel to and one at each side of the rod 469, the rod then lying in the forked upper end of the cam lever 473, and the cam lever 473 moves the rod forwardly to unlock the thread and rearwardly to lock the thread. The bell-crank lever 493 is associated with a clutch mechanism hereinafter described and has on it an arm 505 which is connected by a rod 507 to an arm 509 on the aforesaid bell-crank lever, having the arm 379 which is rocked in an anti-clockwise direction after the stitch forming and work feeding devices come to rest to raise the presser foot. After the stitch forming and work feeding devices have come to rest the bell-crank lever 493 is rocked in a clock-wise direction viewed from the right and the bell-crank lever 483 to which it is connected moves upwardly the rear end of the rod 469. This upward movement of the rear end of the rod 469 takes place about the pivotal connection of the pair of links 471 to the cam lever 473 and the rear end of the rod therefore besides moving upwardly moves forwardly and opens the upper thread lock which at this time in the normal operation of the machine is closed.

A take-up roll 511 (Fig. 4) of the illustrative machine is rotatably mounted on the right hand end of a take-up arm 513 of a bell-crank lever which is pivoted on an eccentric portion 515 of a horizontal forwardly and rearwardly extending shaft 517 which is rotatably mounted in the machine column a little to the left of the centre of the horn and just below the horn.

The bell-crank lever has another arm 519 which has pivoted to its right hand end a depending link 521. The lower end of the link 521 is pivotally connected to the upper end of a pitman 523. The other end of the pitman is pivoted on a crank pin 525 formed on the forward end of the aforesaid take-up shaft 31. The pitman 523 is pivoted to the lower end of a radius arm 527 the upper end of which is pivoted on a horizontal forwardly and rearwardly extending pivot 529 in a casing 531 secured on the column, in which casing the crank pin 525, pitman 523 and radius arm 527 are enclosed. The end of the pitman which is connected to the link 521 is caused, by the crank pin 525 and radius arm 527 to move in a double looped more or less horizontal path and through the link 521 swings the take-up arm upwardly and downwardly to give up and pull down the needle thread at appropriate times in the machine cycle. By adjusting the eccentric portion 515 of the shaft 517 the movement of the take-up roll may be varied in such a manner that the take-up roll moves to a lower position when the stitches are being set and may thus be caused to compensate for differences in the stretch of various threads.

The illustrative machine is provided with an auxiliary take-up which comprises a thread guiding roll 533 arranged between the main take-up and the upper thread lock hereinbefore described. The thread guiding roll 533 is rotatably mounted on the right hand end of one arm 535 of an auxiliary take-up lever 537. The hub of the lever 537 is pivoted on a horizontal stud 539 extending forwardly and rearwardly of the machine beneath the horn and at the left of the axis of the horn. Another arm 541 of the auxiliary take-up lever 537 has pivoted to its left hand end by a horizontal pivot 543 the upper end of a depending link 545 the lower end of which is pivotally connected by a horizontal pin 547 to one arm 549 of a bell-crank lever which is pivoted on a horizontal forwardly and rearwardly extending stud 551 secured in the machine frame directly above the aforementioned take-up shaft 31. Another arm 553 of the latter bell-crank lever has rotatably mounted on it a cam roll 555 which engages in a cam groove in a cam on the take-up shaft 31. The thread passes from the aforementioned upper thread lock of the two thread locks hereinbefore described upwardly and over the auxiliary take-up roll 533 and then downwardly around the underside of the main take-up roll 511 and from the latter upwardly into the horn. The auxiliary take-up therefore takes up thread when it is rising and gives up thread when it is moving downward and the main take-up gives up thread when it is rising and takes up thread when it is moving downward.

The horn 15 of the illustrative machine is of substantially the usual shape of horns commonly used in machines of the kind with which the present invention is particularly concerned.

The horn 15 is secured on a circular plate 557 (Fig. 2) which is rotatably mounted on the aforesaid bracket 13 which is secured to the column. The circular plate 557 has formed on its under face a V-shaped groove which receives a ring of balls 559 which are supported in a circular groove in the upper face of a ring-like portion 561 secured on the aforesaid bracket 13 and forming one ball bearing for the horn. The under face of the ring-like portion 561 has formed in it a circular V-shaped groove in which are arranged a second ring of balls 563. The latter balls are

supported on an upper face of a circular ring 565 secured to the underside of a depending flange on the plate 557, and form a second ball bearing for the horn.

5 The plate 557, its flange and ring 565 shroud the ring-like portion 561. The ball bearing 563 supports the horn heightwise and laterally and the second ball bearing 563 prevents the horn from tipping.

10 The whirl 565 is rotatably mounted in the upper end or tip of the horn and has formed in it usual thread guiding and needle receiving holes. The whirl 565 is rotated twice during each cycle of the machine in an anti-clockwise direction

15 when viewed from above. The whirl 565 has formed on its bevel teeth which mesh with bevel teeth on the upper end of a rod 567 rotatably mounted in the upper portion of the horn. The rod 567 has formed on its lower end bevel teeth

20 which mesh with bevel teeth formed on the upper end of a second rod 569 rotatably mounted in the horn which at its lower end has secured on it a bevel gear 571. The bevel gear 571 meshes with a bevel gear 573 rotatably mounted on a vertical driving sleeve 575 which is rotatably mounted in ball bearings in the horn co-axial with the axis of the latter and in the lower part of the horn.

25 The needle thread after passing around the take-up passes upwardly through the driving sleeve 575 and then around a guide roll 577 just above the upper end of the sleeve. From the latter roll the thread passes upwardly in the horn to the whirl being guided by rollers 579, 581 rotatably mounted in the horn. The guide roll 577 is rotatably mounted on the upper end of a guiding roll sleeve 583 which is mounted in an eccentric bore in the upper end of the driving sleeve 575.

30 The guiding roll sleeve 583 has formed on its upper end a head 585 in a recess in which the roll is pivoted and the recess engaging a rectangular block pivoted on a vertical stud 587 secured in the horn. The block prevents the guiding roll sleeve 575 from rotating with the driving sleeve and the eccentricity of the bore in the driving sleeve in

35 which the guiding roll sleeve 583 is mounted causes the roll to move to and fro as the driving sleeve rotates and drives the whirl. As the whirl rotates its thread guiding hole, owing to its offset portion, relatively to the axis of the whirl,

40 tensions and relaxes the needle thread and the thread guiding roll 577 at the upper end of the guiding roll sleeve is arranged, by its to and fro movement, to counteract the thread tensioning and relaxing action of the thread guiding hole

45 in the whirl so that the tension on the thread is unaffected by the rotation of the thread guiding hole in the whirl. The bevel gear 573 on the vertical driving sleeve 575 is connected to the sleeve by a yielding arrangement so that should the

50 whirl become jammed the sleeve 575 will rotate relatively to the bevel gear 573 and the whirl or bevel teeth will not be broken. The gear 573 has keyed to its underface an inverted cup-shaped washer 589 which surrounds the sleeve. In the

55 cup-shaped washer are two balls 591, one at each side of the sleeve. The balls 591 normally engage vertical recesses 593 in the peripheral face of the sleeve 575 and recesses in the upper face of the cup in the washer. The balls 591 are normally pressed up into the latter recesses by a

60 spring 595 surrounding the sleeve and are held in the recesses 593 in the sleeve 575 by the peripheral wall of the washer. The whirl is therefore driven through the balls 591 and recesses but if

65 the whirl becomes jammed the balls 591 can move

70 in the recesses 593 in the sleeve 575 and the peripheral wall of the washer. The whirl is therefore driven through the balls 591 and recesses but if

75 the whirl becomes jammed the balls 591 can move

80 in the recesses 593 in the sleeve 575 and the peripheral wall of the washer. The whirl is therefore driven through the balls 591 and recesses but if

downwardly against the action of the spring 595 out of the recesses in the upper face of the cup in the washer and travel round with the sleeve by reason of their engagement with the vertical recesses 593 in the sleeve 575 so that no damage to the whirl or its driving connections to the sleeve will occur. The sleeve 575 has secured on its lower end a bevel gear 597 which meshes with an idler bevel gear 599 rotatably mounted on the column and the latter gear meshes with the bevel gear 43 which is driven by the aforesaid thread lock shaft 35.

The barb of the needle is positioned about 20° around the needle stem towards the right hand side of the needle when viewed from the front and of the forward part of the periphery of the needle. By arranging the barb in this position and rotating the whirl in an anti-clockwise direction, when viewed from above, the thread may be laid in the hook of the needle during a comparatively small portion of the rotation of the whirl. If the needle barb were arranged directly at the front of the needle and the whirl were rotated in an anti-clockwise direction the last needle hole might be moved, by swinging of the work during its feed, into such a position forwardly of the path of feeding movement of the awl that the thread might be carried around the needle without being laid on the needle hook and the positioning of the barb around the needle overcomes this difficulty.

The whirl is driven at a varying speed in such a manner that the speed of the whirl is increased while it is wrapping the needle thread around the needle and is decreased during the other or idle part of its rotation.

Such variable speed drive of the whirl is obtained by securing the aforesaid bevel gear 43 on the forward end of a shaft 601 (Figs. 2 and 28) lying forwardly of the thread lock shaft 35 and to the right of the thread lock shaft 35. The forward end of the thread lock shaft 35 and the rear end of the shaft 601 have secured on them crank arms 603, 605 which are connected by a link 607 with the result that the whirl is driven at a varying speed. The whirl during the time that it is wrapping the needle thread around the needle will preferably be driven at a speed of 3 to 1 in relation to the speed of the crank shaft 29 and provision may be made whereby the relative lateral positions of the two shafts may be altered or the shafts may be brought into line so that the speed of the whirl when it is wrapping the needle thread around the needle may be varied or the whirl may be driven at a uniform speed.

Secured on the right hand side of a cover 607, secured on the right hand side of the column, which encloses the thread measuring mechanism is a bracket 609 (Figs. 1 and 29) which has rotatably mounted in it a horizontal forwardly and rearwardly extending needle thread pay-off shaft 611. The shaft 611 has secured on its rear end an upwardly extending arm 613 having a radially extending slot 615 formed in its upper end portion. The slot 615 has adjustably secured in it a stud 617 on which is pivoted one end of a link 619 the other end of which is pivoted to a crank arm 621 on the rear end of the aforesaid thread lock shaft 35. As the latter shaft rotates the thread pay-off shaft is oscillated through the link 619 and arm 613. The extent of oscillation of the thread pay-off shaft 611 may be varied by adjusting the stud 617 in the slot 615 in the arm 613. The forward end of the

pay-off shaft has rotatably mounted on it a sleeve 623 the outer face of which is slightly tapered from front to rear so as to securely hold the core of a roll of thread 625 pressed onto it.

5 The shaft 611 at the rear of the sleeve has secured on it an arm 627 which at its outer end has pivoted on it a pawl 629 having in it a friction pad 631 which is held, by a spring 633 connected to the arm and pawl, in engagement with the peripheral face of a flange 635 formed on the rear end of the sleeve. The thread from the roll passes downwardly to a wax pot 637 of the machine secured on the front of the column and from the wax pot passes upwardly to the thread 10 locks, measuring mechanism and take-up and from the latter passes upwardly through the horn to the whirl. The pawl 629 and arm 627 are so arranged that when the arm is oscillated in one direction the thread roll is more or less 15 positively rotated to pay off thread to the thread measuring mechanism when the latter is measuring off thread and when the arm is oscillated in the other direction the pawl 631 moves back relatively to the flange 635 and by its frictional engagement with the flange may rotate the latter to cause the thread roll to draw back any slack thread between the roll and the lower thread lock which is at that time closed on the thread. 20 The stud 617 in the slot 615 in the arm 613 is preferably so adjusted that as much or a little more thread is paid off from the roll as is drawn by the thread measuring mechanism. Should the thread measuring mechanism require more thread than is paid off from the roll the roll will 25 be rotated by the pull on the thread against the frictional action of the pawl 631. This pay-off mechanism prevents over-running of the thread roll and accumulation of slack thread which might occur if the thread roll were freely rotatable and also serves to pull thread from the roll if the thread through overlapping or other reason is prevented from being freely drawn from the roll. The pawl 629 is preferably moved away 30 from the flange when the machine stops so that the operator may freely draw thread from the roll. The pawl may be connected to the aforesaid clutch and two speed driving mechanism so that when the machine stops it is moved away 35 from the flange or may have on it an arm arrange to engage a stationary cam at one end of its movement which moves the pawl away from the flange and when the machine stops the arm is in engagement with the cam.

Various parts of the illustrative machine are 40 lubricated by oil supplied by a rotary pump from an oil reservoir 639 (Figs. 1 and 30) in the column 1 of the machine. Below the reservoir is an oil filter so constructed that the filter may be removed from the machine for cleaning purposes, 45 without emptying the reservoir. The filter includes a sleeve member 641 (Fig. 30) which is inserted into a horizontal cylindrical chamber 643, formed in the bottom of the reservoir 639, extending forwardly and rearwardly of the machine. The inner end of the sleeve member 641 is closed by a screw plug 645 in the member. The sleeve member 641 has an opening 647 formed in the top of it which is in alignment with an opening 649 leading from the chamber 643 to the reservoir 639 so that oil in the latter can flow 50 into the sleeve member 641. The sleeve member has in it a cylindrical gauze filter 651 secured on the inner end of a cylindrical stem 653 which is pressed into a reduced portion of the bore of the sleeve member 643 near the front thereof.

The stem 653 has a central bore extending through it the front end of which is closed by a screw 655 threaded into it and the stem has formed in it an opening 657 which leads from the central bore in the stem upwardly through a bore 659 in the sleeve member 641 to a bore in a pump bracket 661 secured in the reservoir 639 which leads to a pump chamber in the pump bracket. The front end of the cylindrical chamber 643 in the reservoir 639 is closed and the sleeve member 641 is held in place by a dome-shaped cap 663 screwed into the chamber and enclosing the front end portion of the sleeve member which portion is reduced in diameter and is bored axially from its front end into the bore into which the aforesaid stem 653 is pressed. The opening 649 which leads from the reservoir 639 to the interior of the sleeve member 641 is normally open, but if the dome-shaped cap 663 is removed and the sleeve member 641 and with it the filter 651 are drawn forwardly out of the cylindrical chamber 643 in the reservoir this opening 649 is caused to be automatically closed so that the oil in the reservoir will not escape. The opening is closed by a plug 665 which is pivoted on the forward end of a horizontal arm 667 which is pivoted at its rear end on a horizontal pin 669 in the reservoir. The arm and plug are normally held in a raised position by a vertical plunger 671 which is slidably mounted in the reservoir. The plunger 671 engages at its upper end the arm 667 and at its lower end the sleeve member 641 to hold the arm 667 raised and the plug 665 away from the opening 649 so that the oil can flow from the reservoir into the sleeve member 641 and be drawn through the gauze filter 651 and passages in the stem 653 by the pump. If the sleeve member 641 is withdrawn from the cylindrical chamber the plunger 671 is moved down by a spring plunger 673 behind the end of the sleeve member 641 and the plug 665 closes the opening 649 leading from the reservoir to the cylindrical chamber. The closing of the opening 649 occurs during the withdrawal of the sleeve member 641 before the rear end of the latter passes in front of the opening 649 and the rear end of the sleeve member moves rearwardly of and closes the opening 649 before it engages the plunger 671 and raises it and the plug 665 as the sleeve member is replaced in the chamber. The opening 649 is thus effectively closed before the withdrawal of the sleeve member 641 and is opened after the rear end of the member has passed the opening 649 so that no oil can flow from the reservoir 639 into the cylindrical chamber 643 and from the chamber onto the floor. The aforesaid pump bracket 661 in the reservoir is positioned below the level of the oil in the reservoir and has rotatably mounted in the aforesaid pump chamber in it a pair of spur gears one of which is secured on the lower end of a vertical shaft 675 rotatably mounted in the bracket which shaft has on its upper end a spiral gear 677 (Fig. 2) which meshes with a spiral gear 679 on the aforesaid take-up shaft 31. The other gear is secured on a vertical shaft rotatably mounted in the pump bracket and is driven by the first gear, the gears acting to force the oil from the reservoir along a horizontal passage in the pump bracket. The latter passage in the pump bracket has in it a ball safety valve which may be adjusted to yield under a desired pressure and if the valve yields the oil passing through the valve returns to the reservoir. The pump bracket 661 has in it four vertical holes leading

from the top of the bracket into the aforesaid passage in the bracket. A pipe leads up through the column of the machine from each of the four holes in the pump bracket and the pipes convey oil pumped through them to various parts of the machine.

One pipe 674 passes upwardly through the column and upwardly at the rear of the aforesaid head of the machine. This pipe carries oil to a reservoir 676 and small plunger type pump secured to the rear of the head which may be substantially identical with that illustrated in Patent No. 2,051,250, dated August 18, 1936, to Harold E. Elliott. The small pump supplies oil to the shuttle casing guideway and guide. The plunger 678 of the small pump is actuated, each time the machine is started, to supply a drop of oil to the guideway and guide. The plunger, which is normally raised by a spring, is depressed by a cam lever 680 secured on the aforesaid horizontal rock shaft 381 in the rear of the machine head which is rotated in an anti-clockwise direction after the stitch forming and work feeding devices have stopped. When the machine is started the latter rock shaft is rotated in a clockwise direction and the cam lever depresses the plunger which forces a drop of oil along a pipe 682 at the left hand side of the head to the shuttle casing guideway and guide. The reservoir at the rear of the head has an overflow pipe 684 from which oil, supplied to it by the pump in the column in greater quantity than that used by the plunger pump, drops onto the hereinbefore described needle driving crank and is thrown by the needle crank onto the awl crank and other parts in the head. Another pipe 686 carries oil from the pump bracket to the hereinbefore described spur gears 37, 39, 41 in the column. Yet another pipe 688 carries oil from the pump bracket to the take-up mechanism and another pipe 690 carries oil to the driving shaft to lubricate the clutch mechanism hereinafter described. The oil from the various parts of the machine drains back down the head and column to the reservoir in the column.

The relative timings of the work feeding and stitch forming instrumentalities of the illustrative machine, see Fig. 31, during a single cycle thereof will now be described.

Assuming the machine to be in operation to sew a seam and the work feeding and stitch forming devices to have reached once more the positions which they occupied when the machine came to rest, the awl (see line A in Figure 31) after having entered and fed the work in the previous cycle will have fully risen away from the work and will have moved part-way down again towards the work. The needle and awl will have moved back to the right hand end of their path of movement. The needle (see line B in Fig. 31) will have risen above the work and will be drawing a loop of thread, supplied, so as to prevent reeling of the needle thread in the needle barb, partly by a loop of thread left standing up above the work from the previous stitch and partly by thread given up by the take-up, up through the work. The thread lifter (see line C in Fig. 31) is rising and has just engaged, to carry forward one leg of the loop of thread being drawn up by the needle. The presser foot (see line D in Fig. 31) is down and is holding the work against the horn and is locked (see line E in Fig. 31) against upward movement. The presser foot can however be lifted very slightly as hereinbefore described. The beak of the shuttle cas-

ing is about to enter the loop drawn up by the needle, the beak actually engaging the loop after the crank shaft has rotated through about 40° at which time the thread lifter is dwelling in its highest position. When the work feeding and stitch forming devices have reached the positions which they occupied when the machine came to rest the thread measurer (see line F in Fig. 31) will have measured off thread in accordance with the thickness of the work determined by the presser foot which thread is given up by the thread measurer as the loop of needle thread is being passed over the bobbin case. The top lock (see line G in Fig. 31) is closed and the bottom lock (see line H in Fig. 31) is open. The take-up (see line I in Figure 31) will have risen to give up thread to the needle.

The awl (line A) continues to descend and in doing so enters the work without quite penetrating it and reaches its lowest position when the crank shaft has rotated through about 65° . The awl remains more or less in its depressed position while the crank shaft rotates through about a further 60° . The awl rises slightly during this time and is moved to the left to feed the work (see line J in Figure 31) while the crank shaft rotates from about 65° to about 135° of rotation of the crank shaft. The awl begins to move upwardly out of the work when the crank shaft has rotated about 125° from its starting point. The movement of the awl may be so arranged that after the work has been fed the awl moves downwardly to penetrate the work before it begins to move upwardly.

The thread lifter (line C) reaches its fully raised position after about 25° of rotation of the crank shaft and dwells in its raised position during about 15° of rotation of the crank shaft before it begins to descend. As already mentioned hereinbefore the shuttle beak engages the thread of the loop drawn up by the needle after about 40° of rotation of the crank shaft. The top thread lock (see line G) is closed at this time and the shuttle beak pulls the needle thread loop of the previous stitch which has been drawn down on to the work by the needle into the work to set the previous stitch after the crank shaft has rotated through about 75° from the starting point, as indicated at the bottom of Fig. 31. At the same time as the shuttle beak is setting the previous stitch the take-up (see line I), which has risen part-way to give up thread to the needle, is moved down slightly so that the take-up exerts a downward pull on the needle thread and thereby assists in setting the stitch by taking out any slack there may be in the needle thread between the top lock and the work. When the previous stitch has just been set i. e. after about 75° of rotation of the crank shaft the top lock is opened. The thread measurer (see line F) is arranged to give up more thread than is actually required for each stitch and to draw back this extra thread before it measures thread for the next stitch. At the time in the machine cycle when the previous stitch has just been set and the upper thread lock has just opened the thread drawn from the supply by the thread measurer and the extra thread have been paid out by the thread measurer in readiness to be drawn up by the shuttle casing as it passes the loop of needle thread over the bobbin case. The take-up lever, after the stitch has been set rises comparatively rapidly and gives up thread to the loop being passed over the bobbin case. The thread given up by the thread measurer, which includes that

drawn from the supply as determined by the heightwise position of the presser foot and the extra thread referred to and the thread given up by the take-up provide plenty of slack thread which may readily and rapidly be drawn up by the shuttle casing into the loop of needle thread being passed over the bobbin case.

The awl (line A) commences to rise after the crank shaft has rotated through about 125° and reaches its highest position when the crank shaft has rotated through about a further 90° i. d. when the crank shaft has rotated through about 215° from its starting position. The awl remains in its highest position, except for a slight dipping and rising movement, until the crank shaft has rotated through about 330° from its starting position when it begins to descend again to enter the work during the next cycle.

The needle (line B) reaches its highest position when the crank shaft has rotated through about 35° from its starting position and then moves quickly slightly downwardly to release the hook of the needle from the needle thread, the thread actually being removed from the needle hook after about 50° of rotation of the crank shaft from its starting position. The needle rises again, after dipping, to its original position and commences to move downwardly to pierce the work when the crank shaft has rotated through about 150° from its starting position. The needle reaches its lowest position when the crank shaft has rotated through about 270° from its starting position. The needle dwells in its lowered position while the crank shaft rotates through about 40° during which time the whirl wraps the needle thread around the needle and then the needle commences to rise, drawing up a loop of needle thread through the work.

As aforesaid the movement of the awl towards the left to feed the work (line J) commences when the crank shaft has rotated through about 65° from its starting position and finishes when the crank shaft has rotated through about 135° from its starting position i. e. the feeding of the work takes place during about 70° of rotation of the crank shaft. The awl remains in its left hand position, while it rises out of the work, during about 35° of rotation of the crank shaft. The awl then commences to return and arrives at the end of its movement towards the right when the crank shaft has rotated through about 220° from its starting position. The needle of course moves to and fro with the awl but is above the work during the feeding and return movements of the awl.

The presser foot (lines D and E) is down on the work and is locked against upward movement at the start of the machine cycle. The presser foot can however yield slightly upwardly, as hereinbefore referred to, at this time. The presser foot is raised from the work when the crank shaft has rotated through about 55° from its starting position and moves down into engagement with the work when the crank shaft has rotated through about a further 95° during which time the work is fed by the awl. The slight upward yield of the presser foot is prevented by the cam groove which causes the presser foot to be lifted from the time the presser foot comes down on to the work until the crank shaft has rotated through about 235° from its starting position. The presser is locked against upward movement, except for the slight yield aforesaid, throughout the cycle except when the presser foot is moving down and engages the work after having been

raised during the feeding of the work, the presser foot being unlocked when the crank shaft has rotated through about 130° from its starting position and being locked again when the crank shaft has rotated through about a further 20° . When the presser foot is unlocked it has been moved positively down about half-way from its raised position and is then pressed by its spring against the work. This positive downward movement of the presser foot prevents the operator from tipping the shoe to an undue extent thereby holding the presser foot in a raised position and causing the thread measuring mechanism, which is controlled by the heightwise position of presser foot to draw off more thread than is actually called for by the thickness of the work.

As aforesaid the thread lifter (line C) reaches its highest position when the crank shaft has rotated through about 25° from its starting position and dwells in its fully raised position during about 15° of rotation of the crank shaft when it begins to descend again. The thread lifter reaches a lowered position, about half way between its highest and lowest positions, when the crank shaft has rotated through about a further 45° and remains in this partly lowered position until the crank shaft has rotated through about 165° from its starting position, i. e. its dwells during about 75° of rotation of the crank shaft. The thread lifter then begins to move down to its fully lowered position which it reaches when the crank shaft has rotated through about a further 60° and remains in this position until it begins to rise again near the end of the cycle when the crank shaft has rotated through about 335° from its starting position.

The beak on the shuttle casing is at the beginning of the machine cycle a little at the left of the loop of needle thread when being drawn up by the needle and when, as already mentioned hereinbefore, the crank shaft has rotated through about 40° from its starting position the beak engages that part of the loop of needle thread which extends from the needle to the thread lifter. After the stitch is set the speed of the shuttle casing is accelerated while the loop is being passed over the bobbin case and the speed of the shuttle casing is slowed down while the loop is being drawn down by the take-up and the beak is approaching the next needle loop.

The thread measurer (line F) commences to give up an amount of thread, depending upon the thickness of the work as measured by the presser foot, which it has drawn from the supply in the previous cycle, when the crank shaft has rotated through about 20° from its starting position. The thread measurer finishes giving up this measured amount of thread when the crank shaft has rotated through about a further 30° of rotation of the crank shaft. The thread measurer having given up the measured amount of thread continues to give up more thread which, later in the cycle, it draws down again as the loop of needle thread is being pulled down from the shuttle casing by the take-up. This latter thread giving up movement of the thread measurer continues until the crank shaft has rotated through about 100° from its starting position and provides an accumulation of thread, below the top lock, which may be rapidly drawn up by the shuttle casing as soon as the top lock is opened. The thread measurer then dwells while the crank shaft rotates through about 40° when it begins to draw back the extra thread which it has given up. This drawing back movement of the thread

measurer continues for about another 90° of rotation of the crank shaft when the thread measurer dwells again until it commences to draw from the supply a measured length of thread as determined by the thickness of the work. The thread measurer commences to draw the measured amount of thread from the supply when the crank shaft has rotated through about 300° from its starting position and continues its thread drawing movement until about the end of the cycle.

The top thread lock (line G) is closed at the commencement of the cycle and commences to open when the crank shaft has rotated through about 60° from its starting position and releases the thread when the crank shaft has rotated through about another 20° . The top lock continues to open while the crank shaft rotates through about a further 10° and remains fully open until the crank shaft has rotated through about 230° from its starting position. The top lock then commences to close, gripping the thread after about a further 20° of rotation of the crank shaft and being fully closed about 10° later. The top lock then remains closed until the end of the cycle.

The bottom thread lock (line H) is beginning to close at the commencement of the machine cycle and has been fully closed to grip the thread when the crank shaft has rotated through about 25° . The bottom lock remains closed until the crank shaft has rotated through about 285° from its starting position. The bottom lock then commences to open and is fully opened when the crank shaft has rotated through about a further 30° . The bottom lock remains open while the crank shaft rotates through about 45° and then begins to close.

The take-up (line I) at the beginning of the machine cycle is rising to give up thread to the needle which is also rising. The take-up continues to rise until the crank shaft has rotated through about 30° from its starting position when the take-up moves downwardly somewhat as aforesaid to exert a pull on the needle thread at the time when the previous stitch is set. The take-up is at the lowest point of its dip when the crank shaft has rotated through about 75° from its starting position. The take-up, after dipping, rises rapidly to give up thread to the loop which is being passed over the bobbin case and reaches its highest position when the crank shaft has rotated through about 140° from its starting position. The take-up then immediately begins to descend and reaches its lowest position when the crank shaft has rotated through about 280° from its starting position and then begins to rise again.

The whirl which, when viewed from above, rotates in an anti-clockwise direction and makes two revolutions during each revolution of the crank shaft, wraps the needle thread around the needle when the latter is in its lowest position. The needle thread hole in the whirl is directly in front of the needle when the crank shaft has rotated through about 235° from its starting position and commences to wrap the needle thread around the needle when the crank shaft has rotated through about a further 15° and completes the wrapping of the thread around the needle when the crank shaft has rotated through about 315° from its starting position. The whirl rotates idly during the rest of the cycle.

As hereinbefore described the main take-up is giving up thread to the needle while the crank

shaft is rotating through about the last 85° of one cycle and about the first 30° of the next cycle. When the main take-up commences to move upwardly to give up thread the auxiliary take-up (see dot-and-dash line K) commences to so move relatively to the main take-up that it pulls the needle thread which has just been laid in the needle hook firmly down into the hook, this movement of the auxiliary take-up occurring while the crank shaft rotates from about 290° from its starting position through about 35° while the main take-up is giving up thread. As the main take-up continues to give up thread the auxiliary take-up is so moved that it keeps the thread between the top lock and the work taut. While the crank shaft is rotating from about 30° to 290° the auxiliary take-up is stationary and while the stitch is being set the arm of the auxiliary take-up which carries the thread guiding roll engages a stationary abutment so that the parts of the auxiliary take-up cannot yield at this time.

The illustrative machine may be provided with another thread lock in addition to the two thread locks hereinbefore described. If such a third thread lock is used the auxiliary take-up will not be used and the timing of the main take-up will be somewhat different from that described.

The third lock, if used, is positioned just below the horn (Fig. 37) and engages the needle thread between the take-up and the whirl. The third lock is caused to lock the needle thread while the beak on the shuttle casing is pulling the previous loop into the work and is opened when that stitch has just been set. The third lock comprises a plate 681, similar to the aforesaid plates 437, against which the thread is clamped by a plate 683, similar to the plates 441. The plate 683 has extending from it a stem 685 which is slidably mounted in a boss 687 on the aforesaid bracket 13. The stem has slidably mounted in it a plunger 689 which engages one end of a compression spring 691 in the plunger. The plunger has in it a pin 693 which passes through a slot 695 in the stem. The plunger 689 is connected by a pair of parallel links 697 to an arm 699 of a cam lever 701 which is pivoted on a vertical shaft 703 secured in the bracket 13. Another arm 705 of the cam lever 701 carries a cam roll 707 which enters a cam groove in a cam on the aforesaid take-up shaft 31. The plate 683 is yieldingly pressed, through the spring 691 against the thread and is positively withdrawn by the engagement of the pin 693 with one end of the slot 695. When the third lock is used the timing and driving mechanism of the take-up and the timing of the aforesaid top and bottom thread locks and the thread measurer is somewhat different from that hereinbefore described. The take-up lever 709 is pivoted on the forward end of a horizontal shaft 711. The take-up lever 709 has extending to the left from it an arm 713 which is pivotally connected to one end of a toggle link 715 which extends downwardly and is pivoted at its other end to the right hand end of an arm 716 which is pivoted at its left hand end on a horizontal forwardly and rearwardly extending shaft 717 which is secured in the horn carrying bracket 13. The arm 716 has pivotally connected to it near its right hand end one end of a crank link 719 the other end of which is pivoted on a crank 721, on the take-up shaft 31, corresponding to the crank referred to in the previously described take-up mechanism.

When the third thread lock is used in addition

to the other two thread locks the thread measurer is not arranged to give up and draw back the thread, additional to that which it measured for each stitch, hereinbefore referred to but only to measure thread for each stitch. The take-up is however arranged to provide an accumulation of thread behind the third lock which when the latter lock is opened as that stitch has just been set can be rapidly drawn up by the shuttle beak. When therefore either arrangement of thread locks is used there is provided an accumulation of needle thread which may be freely drawn up by the shuttle casing after the stitch is set.

The timing of the thread measurer, thread locks and take-up when the third thread lock is used will now be described it being understood that the timing of the other devices of the machine is the same as has been already described.

In the starting position of the crank shaft the thread measurer (see line L in Fig. 38) has nearly completed its thread measuring movement. It completes this movement when the crank shaft has rotated through about 25° from its starting position. The thread measurer then immediately begins to give up thread and continues to give up thread until the crank shaft has rotated through about 105° from its starting position. The thread measurer remains stationary until the crank shaft has rotated through about 285° from its starting position and then commences to measure thread for the next stitch.

The third lock (see line M in Fig. 38) is, in the starting position of the crank shaft, closing on the thread and grips the thread when the crank shaft has rotated through about 20° from its starting position. The third lock continues to grip the thread until the crank shaft has rotated through about 75° from its starting position and then releases the thread just as the previous stitch has been set. The third lock continues to open after releasing the thread until the crank shaft has rotated through about a further 40° and remains open until it begins to close when the crank shaft has rotated through about 335° from its starting position.

The top lock (see line N in Fig. 38) hereinbefore referred to is, when the crank shaft is in its starting position, closed and remains closed until the crank shaft has rotated through about 85° from its starting position. The top lock then commences to open and releases the thread when the crank shaft has rotated through about a further 15° and remains open during about another 115° of rotation when it again grips the thread.

The bottom lock (see line O in Fig. 38) has just commenced to close when the crank shaft is in its starting position. It grips the thread when the crank shaft has rotated through about 10° and is fully closed when the crank shaft has rotated through about a further 25° . The bottom lock remains closed until the crank shaft has rotated through about 270° from its starting position when it commences to open and releases the thread when it has rotated through about a further 15° . The bottom lock is fully open when the crank shaft has rotated through about 300° from its starting position and commences to close again when the crank shaft has rotated through about 355° from its starting position.

The take-up (see line P in Fig. 38) is, when the crank shaft is in its starting position, rising and giving up thread to the needle, the third lock being open at this time and therefore allowing

the needle to draw up the thread. The take-up continues to pay out thread after the third lock is closed so that when the third lock is opened upon the setting of the previous stitch there is an accumulation of thread below the third lock paid out by the take-up, which can be quickly drawn up by the beak on the shuttle casing. The take-up continues to give up thread until the crank shaft has rotated through about 110° from its starting position. The take-up then commences to move down and pull the loop needle thread which has been passed over the bobbin case towards the work and completes its downward movement when the crank shaft has rotated through about 280° from its starting position. The take-up dwells in its lowest position during about 40° of rotation of the crank shaft when it begins to rise again to pay out thread to the needle.

The aforesaid clutch and two speed driving mechanism of the illustrative machine is substantially similar to that described in U. S. Letters Patent No. 2,138,403, except that the two speed driving mechanism and the clutch are enclosed in the same housing 497 at the rear of the machine and means is provided whereby the presser foot is raised and the top thread lock is released after the machine has come to rest.

The aforesaid driving shaft 7 of the machine has on its rear end, outside the housing, the pulley or pulleys 9 (hereinbefore referred to). Within the housing 497 (Fig. 32) just in front of the pulley or pulleys is a two speed driving mechanism similar in many respects to that described in said U. S. Patent No. 2,138,403. This two speed mechanism comprises an internally coned member 731 rotatably mounted on and movable along the driving shaft 7. The internally coned member 731 has formed in it internal gear teeth which mesh with a pair of pinions 733 rotatably mounted on studs 735 extending rearwardly from a disc 737 which is rotatably mounted on the driving shaft 7. The pinions are arranged at opposite sides of the axis of the driving shaft and mesh with gear teeth formed on the periphery of the hub of an externally coned member 739 which is secured on the driving shaft 7. The internally coned member 731 is arranged to be moved by the starting treadle of the machine along the driving shaft 7 into engagement with an external coned face on the externally coned member 739. When the treadle is raised the internally coned member 731 is held by a spring in such a position that its internal coned face is out of engagement with the external coned face on the externally coned member 739 and if the driving shaft 7 is being driven the externally coned member 739 which is secured on the shaft drives the pinions.

In the illustrated construction the internally coned member 731 is prevented from rotating in a direction opposite to the direction of rotation of the driving shaft 7 and externally coned member 739 by a roller clutch (Fig. 33) which comprises a ring 741 secured to the internally coned member 731 and a cage 743 which surrounds the ring. The ring 741 has formed in it four recesses in which are rollers 745 which are urged by springs 747 towards the narrow ends of the recesses. The cage 743 has extending from it a boss 748 having in it a recess which receives one end of a dumb-bell 750. The other end of the dumb-bell is received in a recess in a head 753 formed on a stem 755 secured in the casing 487. The cage 743 also has on it a lug 757 which en-

gages the head 753. Rotation of the pinions by the externally coned member 739 tends to rotate the internally coned member 731 in the opposite direction and, since the roller clutch prevents rotation of the internally coned member 731 in this direction, the engagement of the pinions 733 with the internal teeth on the internally coned member 731 causes the disc 737 to be driven in the same direction as the shaft 7, but at a slower speed. When the treadle is raised and the pulley on the driving shaft 7 is being driven, i.e., the machine is not being operated, the disc 737 is being driven at slow speed. The disc 737 is formed on a driving member 759 which has on its front side a coned clutch face 761 having secured on it a leather or like ring 763. The ring 763 is arranged to be engaged by an internally coned face 765 on a clutch member 767, which is slidably mounted on the driving shaft 7, to cause the machine to be driven. The clutch member 767 has a splined connection, indicated at 769, to the aforesaid bevel gear 17 on the forward end of the driving shaft 7 so that the clutch member 767 drives the bevel gear 17 and can move axially relatively to it. The clutch member 767 has formed on it a vertical circular face 771 which is moved into engagement with a leather or like brake ring 773 in the housing. The aforesaid internally coned member 731 has extending rearwardly from it a hub portion 775 which is rotatable on the driving shaft 7. The hub portion 775 has adjustably secured on its rear end a collar 777 and a ball thrust bearing 779 is mounted on the hub 775 against the rear face of the internally coned member 731, there being a space between the front face of the collar 777 and rear face of the thrust bearing 779. A horizontal laterally extending shaft 781 is rotatably mounted in the casing 497 below the driving shaft 7 and has secured on it an upwardly extending forked arm 783, the arms of the fork of which extend one at each side of the hub portion 775 and have pivoted on their upper ends blocks 785 which enter the space between the collar 777 and the thrust bearing 779. The shaft 781 has rotatably mounted on its right hand end outside the casing a forwardly extending arm 786, to the forward end of which is pivotally connected a downwardly extending rod 781. The rod 781 is pivotally connected at its lower end to the forward end of an arm 789 (Fig. 1) which is secured on a horizontal shaft 791 extending laterally of the machine and rotatably mounted in a bearing on the lower end of a dash-pot bracket 793 herein-after referred to. Another arm 795 secured on said shaft 791 has pivotally connected to its forward end a forwardly and downwardly extending treadle rod 793 which at its forward end is pivotally connected to the upper end of a forwardly and upwardly extending arm 795 secured on a horizontal treadle shaft 791 extending laterally of the machine and rotatably mounted in the lower portion of the column. Also secured on the treadle shaft 791 is a forwardly extending treadle rod 799 which projects in front of the column. The treadle is normally raised by a spring.

The aforesaid clutch member 767 has extending forwardly from it a hub 801 which is splined on a rearwardly extending hub 803 of the aforesaid bevel gear 17 on the forward end of the driving shaft. The hub 801 on the clutch member has formed around it a cam groove 805. Springs 806 housed within the hub 801 of the clutch member 767 tend to thrust the latter rearwardly

into engagement with the aforesaid driving member 759. The cam groove 805 is engaged by cam rolls on the upper ends of a pair of clutch trip levers 807, 809, the rolls being at opposite sides of the hub. The clutch trip levers are controlled by latches, one of which is shown at 811, and a dash-pot mechanism similar to those described in said U. S. Patent No. 2,138,403. The latches are controlled by a vertical plate 813, similar to the plate referred to in said patent, and this plate is secured to the upper end of a vertical stem 815 which is pivoted at its lower end to the forward end of an arm 817 which is secured on the aforesaid shaft 791 which is mounted in a bearing on the dash-pot, which shaft is rotated by the treadle and controls, through the mechanism hereinbefore described, the two speed mechanism. The arrangement is such that, as in the machine described in said patent, when the treadle is depressed a comparatively short distance the clutch is closed and the machine is driven at its slow speed and when the treadle is further depressed the machine is driven at its high speed. The machine is stopped, when the treadle is released, by the dash-pot mechanism in the same manner as is the machine described in said patent.

In the illustrated construction, the aforesaid bell-crank lever 493 (Fig. 1) on the clutch housing has a rearwardly extending arm 819 the rear end of which is connected by a ball joint to the upper end of a downwardly extending link 821. The lower end of the link 821 is connected by a ball joint to the left hand end, viewing the machine from the rear, of a more or less horizontal arm 823 (Fig. 34) of a cam actuated bell-crank lever 825 which is pivoted on a forwardly and rearwardly extending stud 827. The bell-crank lever 825 has an upwardly extending cam arm 829 which has secured in its upper end a forwardly and rearwardly extending stud on which is rotatably mounted a cam roll 831. The cam roll 831 is arranged to be engaged by a cam 833 on the aforesaid driving member 759 of the clutch which continues to be rotated, if the pulley 9 is being driven, after the stitch forming and work feeding devices have stopped. The forwardly and rearwardly extending stud 827 on which the cam actuated bell-crank lever 825 is pivoted is secured in a controlling lever 835 which is pivoted on a horizontal laterally extending stud 837 secured in the housing 497. The cam 833, when viewing the machine from the rear, swings the bell-crank lever 825 in an anti-clockwise direction and causes through the link 821 the aforesaid bell-crank lever 493 on the housing to swing in a clockwise direction, viewing the machine from the right, and to raise the presser foot and release the aforesaid top thread lock. When the machine is at rest the cam actuated bell-crank lever 825 has been swung in a direction to raise the presser foot and release the top thread lock by the cam 833 and is held in this position by a spring plunger 839 in the housing which engages the upper end of the arm 829 of the bell-crank lever 825. The aforesaid controlling lever 835 has a downwardly and rearwardly extending arm 841 which has secured in its lower end a horizontal laterally extending stud on which is rotatably mounted a cam roll 843. An arm 845 extends downwardly and forwardly from the aforesaid arm 786 and has formed on its lower end a cam 847 arranged to engage the said cam roll 843. The cam 847 is so arranged relatively to the roll 75

843 that during the first part of the downward movement of the treadle when the treadle is depressed to cause the machine to be started at its slow speed the cam 847 engages the roll 843 and swings the controlling lever 835 in an anti-clockwise direction, viewed from the right, and thus causes the cam arm 829 of the aforesaid bell-crank lever 825 which is pivoted on the controlling lever to be swung forwardly and thus become disengaged from the plunger 839 and also causes the cam roll 831 on the arm 829 to be moved forwardly of the cam 833 so that the said arm 829 can swing inwardly towards the driving shaft 7 and thus allow the presser foot to be moved downwardly onto work which has been placed on the horn and allow the top thread lock to close on the needle thread. The hereinbefore described pin and slot arrangement 499, 501 in the top thread lock mechanism allows the aforesaid bell-crank 493 on the clutch casing to move in a counterclockwise direction when the treadle is depressed to allow the presser foot to be moved down onto the work even if the top lock does not immediately close so that the presser foot will be moved down onto the work just before the machine starts and the top lock may be closed slightly later by the spring 503 which as hereinbefore described normally holds the rear end of the slot 499 against the pin 501. When the treadle is fully released the cam 847 is moved out of the path of the roll 843 on the controlling lever 835 and allows the arm 829 on the bell-crank lever 825 to be swung rearwardly into the path of the cam 833 on the driving member 759 and to be actuated by the cam to cause the presser foot to be raised and the top lock to be released. To ensure however that the raising of the presser foot and release of the top thread lock shall not occur until after the stitch forming and work feeding devices have come to rest the controlling lever 835 has a second arm 849 which extends downwardly and forwardly. The arm 849 has secured on it a block 851 which during operation of the machine engages the end of an arm 853 formed integrally with the bell-crank 854 carrying the latches 811 associated with the clutch tripping mechanism and prevents the cam roll 831 from being moved into the path of the cam 833 on the driving member until the stitch forming and work feeding devices have stopped moving the latch-supporting bell-crank in a clockwise direction as shown in Fig. 32, and as fully described in said Patent No. 2,138,403, when the arm 853 moves out of the path of the block 851 and allows the cam roll 831 to move into the path of the cam 833 which thereafter causes the presser foot to be raised and the top thread lock to be released. The presser foot is therefore held down onto the work until the stitch forming and work feeding devices have stopped and prevents the work from being raised from the horn by the needle which is then rising with a loop of thread extending from the work in its hook. When the treadle is depressed further, after having been depressed far enough to allow the presser to move down onto the work, the latches 811 are released from the clutch trip lever 807, 809 and the springs 806 move the clutch member 761 rearwardly to close the clutch and cause the machine to be driven at its slow speed. Upon still further depression of the treadle a spring plunger 855 (Fig. 32) in the arm 845 engages a screw 857 in an arm 859 which is secured on the

shaft, 781, and moves the shaft in a direction to cause through the forked arm, 783, the internally coned member, 731, to be moved into engagement with the externally coned member, 739, and the driving shaft to be driven at its high speed. A spring, 861, normally holds the internally and externally coned members disengaged from each other.

The dumb-bell, 751, hereinbefore described, allows the cage, 743, of the aforesaid roller clutch to move with the internally coned member, 731, towards and from the externally coned member, 739, and also returns the controlling lever, 825 and arm, 829, towards the right in Fig. 32.

It will be apparent that, if the operator depresses the treadle only far enough to allow the presser to engage the work, and then allows the treadle to rise, the spring, 861, will return the arm, 829, towards the right in Fig. 32, and so position the cam roll, 831, that the cam, 833, will raise the presser without the machine having been started. The operator is therefore readily able to cause the presser to be raised if he finds it is not properly positioned on the work after he has allowed it to move downwardly.

The aforesaid clutch and two-speed driving mechanism of the illustrative machine causes the machine to stop with a loop of thread extending from the work to the needle which loop has just been drawn through the work by the needle and is therefore somewhat taut. Owing to the tautness of the loop, the operator may have some difficulty in quickly removing the loop from the hook of the needle. To enable the loop of thread to be speedily removed from the hook of the needle when the machine stops the direction of rotation of the various shafts of the machine is reversed slightly after the machine comes to rest so that during such reversal the hook of the needle will descend slightly and either free itself from the loop or allow the loop to be readily removed therefrom. This arrangement in the illustrative machine consists in allowing the aforementioned leather or like brake ring, 773, to yieldingly rotate somewhat and to be returned to the position in which it normally caused the machine to stop. The brake ring, 773, has extending from it three bosses, one of which is shown at 863 (Fig. 35) equally spaced apart around the ring. Each boss has in it a recess, 865, having tapered walls. Each recess, 865, is engaged by the tapered end of a spring plunger, 867, which allows the brake ring to rotate slightly and then returns it to its normal stopping position as aforesaid.

The illustrative machine may be provided with means for lubricating the needle and such means may conveniently comprise a brush, slidably mounted in a tube to which lubricant is supplied, the brush being moved into engagement with the needle upon the stopping of the machine and being withdrawn as the machine is started. The tube which is indicated at 869 (Fig. 10) lies comparatively close to the rear of the shuttle beak and assists somewhat in preventing a loop of needle thread which is being pulled down after having been passed over the bobbin case from falling laterally into the path of the needle and being engaged thereby.

Certain features of the invention relating specifically to lubricating devices, form the subject-matter of a divisional application, Serial No. 442,644, filed May 12, 1942, for Improvements in lubricating systems.

It will be understood that the invention is not limited to the specific embodiment shown, and

that various deviations may be made therefrom without departing from the spirit and scope of the appended claims.

What is claimed is:

5. A lockstitch sewing machine having, in combination, stitch forming devices including a hook needle, a work piercing awl arranged to feed the work, and a loop taker at the side of the work with the needle and awl, a rotatably adjustable work supporting horn, a presser foot, and means for moving the needle and awl together along the line of the seam while feeding the work.
10. 2. A lockstitch sewing machine having, in combination, stitch forming devices including a hook needle, a work piercing awl arranged to feed the work, and a loop taker at the side of the work with the needle and awl, a rotatably adjustable work supporting horn, a presser foot, and carrier means for the needle and awl movable in the line of feed, and on which they are arranged to move together along the line of the seam.
15. 3. A lockstitch sewing machine having, in combination, stitch forming devices including a hook needle, a work piercing awl, and a loop taker at the side of the work with the needle and awl, a work supporting horn, a presser foot, actuating means for the needle and awl, a carrier on which the needle and awl are spaced apart the length of one stitch in the line of feed and with which they are arranged to move together along the line of the seam, and means for advancing said carrier in the line of feed with the awl in the work, and for back feeding said carrier to bring the needle in line with the awl hole.
20. 4. A shoe sewing machine having, in combination, a hook needle, a rotatable work supporting horn arranged to extend within the shoe, needle threading mechanism in the horn, and supporting and actuating means for the needle comprising an arm, on which the needle is secured, pivotally supported a substantial distance rearwardly of the line of feed, to cause the needle moving circumferentially about said pivot to pass through the work into the horn in a substantially straight path.
25. 5. A shoe sewing machine having, in combination, stitch forming devices including a hook needle, a work piercing awl, a rotatable work supporting horn arranged to extend within the shoe, a presser foot, and supporting and actuating means for the needle and awl including needle and awl supporting arms pivotally supported a substantial distance rearwardly of the line of feed to cause the needle and awl to pass through the work in substantially straight paths, and means for oscillating the needle and awl about said pivots.
30. 6. A lockstitch shoe sewing machine having, in combination, stitch forming devices including a curved hook needle, a work piercing awl arranged to feed the work, and a loop taker at the side of the work with the needle and awl, a work supporting horn, needle threading means in the horn, a feed carrier movable about a pivotal axis substantially perpendicular to the work supporting surface of the horn, and spaced rearwardly of the line of feed, and means on said carrier for supporting the awl, actuating means for the needle and awl, and means for moving said carrier and awl supported thereon about said pivotal axis with the awl in the work to feed the work.
35. 7. A lockstitch sewing machine having, in combination, stitch forming devices including a hook needle, a work piercing awl, and a loop taker at the side of the work with the needle and awl,

a work supporting horn, a presser foot, a feed carrier movable about a pivotal axis substantially perpendicular to the work supporting surface of the horn, and spaced rearwardly of the line of feed, and means on said carrier for supporting the needle and awl a fixed distance apart of one stitch, actuating means for the needle and awl, and means for moving the carrier about said pivotal axis with the awl in the work to feed the work, and for back feeding the carrier to bring the needle in line with the awl hole.

8. A lockstitch sewing machine having, in combination, stitch forming devices including a hook needle, a work piercing awl, and a loop taker at the side of the work with the needle and awl, a work supporting horn, a presser foot, needle and awl supporting arms, pivotally supported a substantial distance rearwardly of the line of feed to cause the needle and awl to follow substantially straight paths through the work, and a carrier pivoted about an axis substantially perpendicular to and located rearwardly of the supporting surface of the horn on which the needle and awl arms are supported and with which they are arranged to move together along the line of the seam.

9. A lockstitch sewing machine having, in combination, stitch forming devices including a hook needle, a work piercing awl and a loop taker at the side of the work with the needle and awl, a work supporting horn, a presser foot, a carrier on which the needle and awl are supported apart in the line of feed a distance of one stitch, and with which they are arranged to move together along the line of the seam, means for moving the carrier to feed the work with the awl in the work, and for back feeding the carrier to bring the needle in line with the awl hole, means for adjusting the length of stitch, and means for adjusting the spacing of the needle and awl on the carrier.

10. A lockstitch shoe sewing machine having, in combination, stitch forming and work feeding devices including a work piercing implement, a rotatably adjustable work supporting horn, a swinging arm on which said work piercing implement is mounted, a pivotal support for said arm located at a substantial distance to the rear of the line of feed to cause said implement to move in a substantially straight path through the work, a crank, a radius arm pivoted to the pitman, and connections between said first-named pivoted arm and the pitman whereby the arm is oscillated from the pitman and including a link pivoted to the pitman at a point on the pitman spaced from its pivotal connection with the radius arm.

11. A lockstitch sewing machine having, in combination, stitch forming devices including a hook needle, a work piercing awl and a loop taker at the side of the work with the needle and awl, a rotatably adjustable work supporting horn, a presser foot, a needle arm and a pivotal support for said arm located a substantial distance to the rear of the line of feed to cause the needle to move in a substantially straight path to enter the horn, and connections for oscillating the needle about its pivot including a crank, a radius arm, a pitman and a link connecting the pitman with the needle arm, said parts being arranged to cause the needle to have a quick dip at the limit of its loop drawing stroke to free the loop from the needle, and thereafter a gradual downward movement toward the work.

12. A lockstitch sewing machine having, in

combination, stitch forming devices including a hook needle, a work piercing awl and a loop taker at the side of the work with the needle and awl, a rotatably adjustable work supporting horn, a presser foot, supporting and actuating connections for the awl including an awl arm and a pivotal support for the awl arm spaced rearwardly of the line of feed, means for moving the awl arm and awl to feed the work, and means for oscillating the awl about its pivot including a crank, a radius arm, a pitman, and a link connecting the pitman with the awl arm, said parts being arranged to cause the awl to penetrate the work, and thereafter to be slightly raised from its low position during the work feed.

13. A lockstitch sewing machine having, in combination, stitch forming devices including a hook needle, a work piercing awl and a loop taker at the side of the work with the needle and awl, a rotatably adjustable work supporting horn, a presser foot, and supporting and actuating means for the needle and awl including needle and awl supporting arms having horizontally arranged pivotal supporting means spaced rearwardly a substantial distance from the line of feed, a crank shaft, a needle crank on said shaft, and connections therefrom for actuating the needle arm, and an awl crank on said shaft and connections therefrom for actuating the awl.

14. A shoe sewing machine having, in combination, stitch forming and work feeding devices comprising a hook needle, a work piercing awl at the side of the work with the needle, a holder for each of the needle and awl movable toward and away from the work, and means for maintaining said holders a fixed distance apart in the line of feed during their movements toward and from the work, at least one of said needle and awl having the held portion thereof offset from the work engaging portion thereof away from the other of said elements in the line of feed.

15. A shoe sewing machine having, in combination, stitch forming and work feeding devices comprising a hook needle, a work piercing awl at the side of the work with the needle, holders with which the needle and awl are movable toward and away from the work, and means for maintaining said holders a fixed distance apart in the line of feed during their movements toward and from the work, at least one of the needle and awl having the held portion thereof offset with relation to the work engaging portion away from the other of said elements in the line of feed, and carrier means on which the holders and needle and awl held thereby are supported a fixed distance apart in the line of feed and for movement together in the line of feed.

16. A shoe sewing machine having, in combination, stitch forming devices including a hook needle, a work piercing awl at the side of the work with the needle, a rotatable work supporting horn arranged to extend within the shoe, a presser foot, needle and awl supporting arms pivotally supported a substantial distance rearwardly of the line of feed to cause the needle and awl to follow substantially straight paths through the work, and a carrier on which the needle and awl arms are supported and with which they are arranged to move together along the line of the seam, the awl having the held portion thereof offset from the work engaging portion away from the needle along the line of the seam.

17. A lockstitch sewing machine having, in combination, stitch forming and setting devices

including a hook needle, a thread case, and a loop taker arranged to carry a loop of needle thread over the thread case, a thread lock, and means for closing the lock to cause the loop taker to set the preceding stitch against the thread lock during its loop drawing stroke, and for opening said thread lock prior to the completion of said loop drawing stroke of the loop taker, said devices including means for providing an accumulation of slack thread on the supply side of the thread lock while the previous stitch is being set.

18. A lockstitch sewing machine having, in combination, devices for supporting the work including a rotatable shoe entering horn, stitch forming and setting devices including a hook needle, a thread case, a loop taker arranged to set the preceding stitch and thereafter to carry a loop of needle thread over the thread case, a thread lock, and means for closing the lock to cause the loop taker to set the preceding stitch against the thread lock, and thereafter for opening the thread lock during the loop drawing stroke of the loop taker, said devices including take-up means arranged to give up thread to the needle and loop taker, pull-off means for measuring new thread from the supply and including means for providing an accumulation of slack thread on the supply side of the thread lock while the stitch is being set.

19. A lockstitch sewing machine having, in combination, stitch forming and setting devices including a hook needle, a thread case, a loop taker arranged to set the preceding stitch and thereafter to carry a loop of needle thread over the thread case, a thread lock, and means for closing the lock to cause the loop taker to set the preceding stitch against the lock, and thereafter for opening the lock during the loop drawing stroke of the loop taker, said devices including take-up means for giving up thread to the needle and loop taker, pull-off means for measuring new thread from the supply, at least one of said take-up and pull-off means being located on the supply side of said thread lock, and means for actuating said devices to provide an accumulation of slack thread on the supply side of the thread lock while the stitch is being set to be drawn upon the loop taker when the thread lock is released.

20. A lockstitch sewing machine having, in combination, stitch forming and setting devices including a hook needle, a thread case, a loop taker arranged to set the preceding stitch and thereafter to carry a loop of needle thread over the thread case, a thread lock, and means for closing the lock to cause the loop taker to set the preceding stitch during its loop drawing stroke, and to open said thread lock prior to the completion of its loop drawing stroke, take-up means arranged to give up thread to the needle and loop taker, pull-off means for measuring new thread from the supply, at least one of said take-up and pull-off means being located on the supply side of said lock, said means being arranged to provide an accumulation of slack thread on the supply side of the thread lock while the stitch is being set, a second thread lock located on the supply side of all of said devices, and means for closing said latter lock when the first-mentioned lock is opened.

21. A lockstitch sewing machine having, in combination, stitch forming and setting devices including a hook needle, a thread case and a loop taker arranged to set a preceding stitch and

thereafter to carry a loop of needle thread over the thread case, a thread lock, and means for closing the lock to set the previous stitch during the loop drawing stroke of the loop taker and to open said lock prior to the completion of the loop drawing stroke, and a take-up device movable to give up thread to the needle and loop taker, and means for imparting to the take-up device a motion to assist in the setting of the previous stitch by the loop taker against said thread lock.

22. A lockstitch sewing machine having, in combination, stitch forming and setting devices including a hook needle, a thread case, a loop taker arranged to set the preceding stitch and to carry a loop of thread over the thread case, a thread lock and means for closing the lock to cause the loop taker to set the previous stitch against the lock during the loop drawing stroke of the loop taker, and to open said lock prior to the completion of the loop drawing stroke of the loop taker, a take-up located between the thread lock and the loop taker movable to give up thread to the needle, to draw in thread during the setting of the previous stitch by the loop taker against said thread lock, and thereafter to give up further thread to the loop taker, a thread measuring pull-off located on the supply side of said thread lock, and means for actuating said pull-off to draw from the supply an amount of thread in excess of that required for the next stitch, and thereafter to give up said excess thread to the loop taker as the thread lock is opened.

23. A lockstitch sewing machine having, in combination, stitch forming and setting devices including a hook needle, a thread case, and a loop taker arranged to set the preceding stitch and thereafter to carry a loop of needle thread over the thread case, a thread lock, and means for closing the lock to set the previous stitch during the loop drawing stroke of the loop taker, and to open said lock prior to the completion of said loop drawing stroke, a take-up device located between the thread lock and the loop taker movable to give up thread to the needle, to draw back thread during the setting of the previous stitch and thereby assist in the setting of the previous stitch by the loop taker against said thread lock, and thereafter to give up further thread during the continued loop drawing stroke of the loop taker.

24. A lockstitch sewing machine having, in combination, stitch forming and setting devices including a hook needle, a needle threading device, a thread case, and a loop taker arranged to set the preceding stitch and thereafter to carry a loop of needle thread over the thread case, a thread lock, and means for closing the lock to set the previous stitch during the loop drawing stroke of the loop taker, and to open said lock prior to the completion of said loop drawing stroke, an auxiliary take-up device operable during the threading and loop drawing stroke of the needle, a main take-up device located between the thread lock and the loop taker movable to give up thread to the needle, to draw back thread during the setting of the previous stitch and thereby assist in the setting of the previous stitch by the loop taker against said thread lock, and thereafter to give up further thread during the continued loop drawing stroke of the loop taker.

25. A lockstitch sewing machine having, in combination, stitch forming and setting devices including a hook needle, a thread case, a loop taker arranged to set the preceding stitch and to

carry a loop of thread over the thread case, a thread lock, and means for closing the lock to cause the loop taker to set the previous stitch against the lock during the loop drawing stroke of the loop taker, and to open said lock prior to the completion of the loop drawing stroke of the loop taker, a take-up located on the supply side of the thread lock arranged to give up thread during the setting of the previous stitch whereby an accumulation of slack thread is provided on the supply side of the thread lock to be drawn in by the loop taker when the thread lock is released.

26. A lockstitch sewing machine having, in combination, stitch forming and setting devices including a hook needle, a thread case, and a loop taker arranged to set the preceding stitch and thereafter to carry a loop of needle thread over the thread case, a thread lock, and means for closing the lock to set the stitch during the loop drawing stroke of the loop taker and to open said lock prior to the completion of the loop drawing stroke of the loop taker, and take-up devices located on the supply side of said thread lock movable to give up thread continuously during the loop drawing movement of the needle and loop taker whereby an accumulation of slack thread is provided on the supply side of said thread lock while the stitch is being set.

27. A lockstitch sewing machine having, in combination, stitch forming and setting devices including a hook needle, a thread case, a loop taker arranged to set the previous stitch and to carry a loop of needle thread over the thread case, a thread lock, and means for closing the lock to set the stitch during the loop drawing stroke of the loop taker and to open said lock prior to the completion of said loop drawing stroke, a take-up device located on the supply side of said thread lock movable to give up thread continuously during the loop drawing movements of the needle and loop taker whereby an accumulation of slack thread is provided on the supply side of said thread lock while the stitch is being set, an additional pair of thread locks located on the supply side of the take-up device, a thread measuring device arranged to act on the thread between said latter thread locks, and means for actuating said pair of thread locks in timed relation to the thread measuring device.

28. A lockstitch sewing machine having, in combination, stitch forming and setting devices including a hook needle, a thread case, a loop taker arranged to set the previous stitch and to carry a loop of needle thread over the thread case, a take-up arranged to give up thread to the needle and loop taker, a thread pull-off, a thread lock between the take-up and pull-off, means for closing said thread lock to cause the loop taker to set the previous stitch against the thread lock, and for opening said lock prior to the completion of the loop drawing stroke of the take-up, and means for actuating the thread measuring pull-off to draw from the supply an amount of thread in excess of that required for the next stitch, and to give up said thread to the loop taker during its loop drawing stroke.

29. A lockstitch sewing machine having, in combination, stitch forming and setting devices including a hook needle, a thread case, a loop taker arranged to set the preceding stitch and to carry a loop of needle thread over the thread case, a take-up arranged to give up thread to the needle and loop taker, a thread measuring pull-off, a thread lock between the pull-off and take-

up, a second thread lock on the supply side of the pull-off, means for closing the former of said thread locks to set the previous stitch during the loop drawing stroke of the loop taker, and for opening said lock prior to the completion of the loop drawing stroke of the loop taker, means for opening said latter thread lock to permit drawing of additional thread from the supply and for closing said latter lock when the former of said locks is open, and means for actuating the thread measuring pull-off to draw in an amount of thread in excess of that required for the new stitch, and thereafter to give up said additional thread to the loop taker.

30. A lockstitch sewing machine having, in combination, stitch forming devices including a hook needle, a shuttle having therein a thread case, means actuating the shuttle to carry the needle loop over the thread case, and a shuttle race yieldably supported to permit rotation of the race with the shuttle in the event that the shuttle becomes jammed in the race.

31. A lockstitch sewing machine having, in combination, stitch forming devices including a hook needle, a shuttle having therein a thread case, means actuating the shuttle to carry the needle loop over the thread case, a shuttle race, a support on which the race is supported to yield in the event that thread becomes jammed between the shuttle and race, and means rendered operative by continued movement of the shuttle to sever the jammed thread portion.

32. A lockstitch sewing machine having, in combination, stitch forming devices including a hook needle, a shuttle having therein a thread case, means for rotating the shuttle to carry the needle thread over the thread case, a shuttle race, a support on which the race is mounted to rotate with the shuttle, and means for holding the race normally stationary arranged to permit rotation of the race with the shuttle in the event that the shuttle becomes jammed in the race.

33. A lockstitch sewing machine having, in combination, stitch forming devices including a hook needle, a shuttle having therein a thread case, means for rotating the shuttle to carry the needle loop over the thread case, a shuttle race, a support on which the race is mounted to rotate with the shuttle, means for holding the race normally stationary arranged to permit rotation of the race with the shuttle in the event that thread becomes jammed between the race and the shuttle, and thread cutting means rendered operative by movement of the race with the shuttle in its support to sever the jammed thread portion.

34. A lockstitch sewing machine having, in combination, stitch forming devices including a hook needle, a shuttle having therein a thread case, means for rotating the shuttle to carry the needle loop over the thread case, a shuttle race, a support having formed therein a guideway in which the race is mounted to rotate with the shuttle, means for holding the race normally stationary arranged to permit rotation of the race with the shuttle in the event that thread becomes jammed between the shuttle and race, and cooperating cutting surfaces formed on the guideway and race rendered operative by movement of the race with the shuttle to sever the jammed thread portion.

35. A lockstitch sewing machine having, in combination, stitch forming devices including a hook needle, a shuttle having therein a thread

case; means for rotating the shuttle to carry the needle loop over the thread case, a shuttle race, a support on which the race is mounted to rotate with the shuttle, yieldable holding means for holding the race normally stationary arranged to permit rotation of the race with the shuttle in the event that the shuttle becomes jammed in the race, said holding means including a device for positively limiting movement of the race with the shuttle in a reverse direction to reset the race.

36. A lockstitch sewing machine having, in combination, stitch forming devices including a hook needle, a shuttle having therein a thread case, means for rotating the shuttle to carry the needle loop over the thread case, a shuttle race, a support in which the race is mounted to rotate with the shuttle, means for controlling the relative position of the race and support comprising a holding element yieldingly supported on one of said parts and cooperating engaging surfaces on the other of said parts, said surfaces including a cammed holding surface arranged to permit rotation of the race with the shuttle in the event that the shuttle becomes jammed in the race, and a positive stop surface for limiting movement of the race with the shuttle in a reverse direction to reset the race.

37. A lockstitch sewing machine having, in combination, stitch forming devices including a hook needle, a rotary shuttle having therein a thread case, and having a broad nose bifurcated hook, a shuttle race engaging a guideway in the shuttle arranged to pass through said bifurcated hook, a support on which the race is mounted to rotate with the shuttle, and means for holding the race normally stationary arranged to permit rotation of the race with the shuttle in the event that thread becomes jammed between the shuttle and the race.

38. A lockstitch sewing machine having, in combination, stitch forming devices including a hook needle, a rotary shuttle having therein a thread case and having a broad nose bifurcated hook, a shuttle race engaging a guideway in the shuttle arranged to pass through said bifurcated hook, a support on which the race is mounted to rotate with the shuttle, means for holding the race normally stationary arranged to permit rotation of the race with the shuttle in the event that thread becomes jammed between the shuttle and the race, and cooperating cutting surfaces formed on the race and support rendered operative by movement of the race with the shuttle to sever the jammed thread portion.

39. A lockstitch sewing machine having, in combination, stitch forming devices including a hook needle, a rotary shuttle having therein a thread case and having a shuttle hook, said stitch forming devices being constructed and arranged to cause the shuttle hook to set the previous stitch, and thereafter to carry the loop of needle thread over the thread case, a shuttle race, a support on which the race is mounted to rotate with the shuttle, means for holding the race normally stationary arranged to permit rotation of the race with the shuttle in the event that thread becomes jammed between the shuttle and the race, and thread cutting means rendered operative by movement of the race to sever the jammed thread portion.

40. In a lockstitch shoe sewing machine, the combination with the other stitch forming devices including a shuttle of a hook needle, a loop spreader, and supporting means on which the

loop spreader is movable across the line of feed, said movement including a component movement in the line of feed toward the needle to engage the loop spreader with the supply side of the needle loop, and thereafter a component movement in the line of feed away from the needle to spread the loop for the entrance of the shuttle.

41. In a lockstitch shoe sewing machine, the combination with the other stitch forming devices including a shuttle of a hook needle arranged with its barb facing at an angle to the line of feed on the shuttle side of the needle, a horn arranged to extend within the shoe, a needle threading mechanism located within the horn, a loop spreader movable in an arcuate path across the line of feed, said movement including a component movement of the loop spreader in the line of feed toward the needle to engage the supply side of the needle loop, and thereafter a component movement in the line of feed away from the needle to spread the loop for the entrance of the shuttle, and means for supporting and actuating the loop spreader.

42. A lockstitch shoe sewing machine, having, in combination, stitch forming devices including a hook needle movable in an arcuate path, a shuttle located to the front side of the needle, a horn arranged to extend within the shoe, needle threading mechanism located within the horn, a loop spreader movable in an arcuate path transversely of the line of feed, said movement including a component movement in the line of feed toward the needle to engage the loop spreader with the supply side of the needle loop, and thereafter a component movement in the line of feed away from the needle to spread the loop for the entrance of the shuttle, and a pivoted support for the loop spreader having its axis located above the sewing point and extended upwardly at a substantial angle to the line of feed and transversely thereof away from the shuttle.

43. In a lockstitch shoe sewing machine, the combination with the other stitch forming devices including a shuttle of a hook needle having its barb facing in a direction generally away from the shuttle and toward the shuttle side of the line of feed, a horn arranged to extend within the shoe, a needle threading whirl located in the horn, means for rotating the whirl in the direction to carry the thread first to the shuttle side of the needle, a loop spreader movable in an arcuate path across the line of feed, said movement including a component movement in the line of feed toward the needle to engage the loop spreader with the supply side of the needle loop, and thereafter a component movement in the line of feed away from the needle to spread the loop for the entrance of the shuttle.

44. A lockstitch shoe sewing machine having, in combination, stitch forming devices including a hook needle movable in an arcuate path and having the barb positioned at an angle in the order of 20° to the right from the front of the needle, a shuttle located at the front side of the needle, a horn arranged to extend within the shoe, a needle threading whirl located in the horn, and means for rotating the whirl in a counterclockwise direction and at varying speed during each rotation of the whirl.

45. A lockstitch shoe sewing machine having, in combination, stitch forming devices including a hook needle movable in an arcuate path and having the barb positioned at an angle in the order of 20° to the right from the front of the

needle, a shuttle located at the front side of the needle and rotatable on an axis extending rearwardly and having a slight downward inclination, a horn arranged to extend within the shoe, a needle threading whirl located in the horn, means for rotating the whirl in a counterclockwise direction, a loop spreader having an arcuate movement transversely of the line of feed to engage with the supply side of the needle loop and spread the loop for the entrance of the shuttle, and a support for the loop spreader movable about an axis located above the sewing point and extending upwardly to the right at an angle in the order of 50° to the line of feed, and rearwardly at an angle in the order of 60° to said line.

46. A sewing machine having, in combination, stitch forming devices including means to pull off thread from the supply as needed, a rotatable supporting means for a wound mass of thread from which thread is supplied to the stitch forming devices, and actuating connections for rotating the supporting means independently of the pull on the thread to pay out thread from the thread mass to the stitch forming devices.

47. A sewing machine having, in combination, stitch forming devices including means to draw off thread from a supply as needed, means for rotatably supporting a wound mass of thread from which thread is supplied to the stitch forming devices, and actuating connections for intermittently rotating said supporting means independently of the pull on the thread and in timed relation to said thread draw-off means to pay out thread to the stitch forming devices.

48. A sewing machine having, in combination, stitch forming devices including means to pull off thread from a supply as needed, means for rotatably supporting a wound mass of thread from which thread is supplied to the stitch forming devices, and means for intermittently rotating said supporting means in timed relation to said pull-off means to pay out thread to the stitch forming devices, and alternately for rotating said supporting means in a reverse direction to take up slack thread between said thread mass and stitch forming devices.

49. A sewing machine having, in combination, stitch forming devices, a thread measuring pull-off for measuring thread from the supply, a thread lock between the pull-off and the supply, means for rotatably supporting a wound mass of thread from which thread is supplied to the stitch forming devices, actuating means having a yieldable connection with said supporting means arranged for intermittently rotating the supporting means to pay out thread to the thread measurer, and alternately for urging the supporting means in the reverse direction to take up slack thread between the thread mass and the thread lock.

50. A sewing machine having, in combination, stitch forming devices, means for rotatably supporting a wound mass of thread from which thread is supplied to the stitch forming devices, including a surface rotating in unison with such wound mass, a friction pawl arranged to engage said surface, and means for oscillating said pawl to intermittently rotate said supporting means to pay out thread to said stitch forming devices.

51. A sewing machine having, in combination, stitch forming devices, means for rotatably supporting a wound mass of thread from which thread is supplied to the stitch forming devices, including a surface rotating in unison with such

wound mass, a friction pawl engaging said surface, and means oscillating said pawl in timed relation to said stitch forming devices including a crank and an actuating connection between the crank and the pawl.

52. A sewing machine having, in combination, stitch forming devices, including means for measuring the thread from the supply for each succeeding stitch, means for rotatably supporting a wound mass of thread from which thread is supplied to the stitch forming devices, including a surface rotating in unison with said wound mass, a friction pawl engaging said surface, means for oscillating said pawl for intermittently rotating the supporting means to pay off thread from the mass, and means for adjusting the extent of the oscillatory movement.

53. A sewing machine having, in combination, stitch forming devices including a thread measuring pull-off for drawing measured amounts of thread from the supply for the formation of each succeeding stitch, rotatable supporting means for a wound mass of thread from which the thread is supplied to the stitch forming devices, an oscillating pawl for intermittently rotating the supporting means to pay off thread from the mass, adjusting means for controlling the amount of thread measured by the thread pull-off, means for oscillating the pawl, and adjusting means for controlling the operation of the pawl to adjust the incremental rotational movements imparted to the supporting means by said pawl.

54. A lockstitch outsole shoe sewing machine having, in combination, stitch forming devices including a hook needle, a work support, a presser foot movable toward and from the work support, a thread measuring pull-off, actuating means for the pull-off, a device for modifying the operation of said actuating means to vary the amount of thread drawn from the supply, power operated positioning mechanism connected to position said device during each stitch forming cycle, and means actuated from the presser foot for controlling the operation of said power operated positioning mechanism to position said device and thereby to determine the amount of thread measured from the supply in accordance with the thickness of the work.

55. A lockstitch shoe sewing machine having, in combination, stitch forming devices including a hook needle, an awl, actuating means including an awl actuating mechanism, a work support, a presser foot movable toward and from the work support, a thread measuring pull-off, actuating means for the pull-off, a device for modifying the operation of said actuating means to vary the amount of thread drawn from the supply, positioning mechanism driven from the awl actuating mechanism connected to position said device during each stitch forming cycle, and means actuated from the presser foot for controlling the operation of said positioning mechanism to position said device and thereby to determine the amount of thread measured from the supply in accordance with the thickness of the work.

56. A lockstitch shoe sewing machine having, in combination, stitch forming devices including a hook needle, an awl, actuating means including an awl actuating mechanism, a work support, a presser foot movable toward and from the work support, a thread measuring pull-off, means for actuating the pull-off comprising a swinging link and connections between one end of the link and the pull-off, positioning mechanism compris-

ing a pivoted support for the fulcrum of the link driven by the awl actuating mechanism for adjusting the fulcrum of the link about said end of the link when in alignment with the support pivot at one limit of the swinging movement of the link to vary the extent of the movements imparted to the pull-off, and means controlled by the position of the presser foot against the work for adjusting the operation of said positioning mechanism to determine the amount of thread measured from the supply in accordance with the thickness of the work.

57. A lockstitch outsole shoe sewing machine having, in combination, a sewing head, a shoe supporting horn, stitch forming devices including a hook needle, a presser foot on the head movable toward and from the horn, a thread measuring pull-off and actuating means for the pull-off located below the horn, a device for modifying the operation of said actuating means to vary the amount of thread drawn from the supply, power operated positioning mechanism connected to position said device during each stitch forming cycle, and adjusting means in the head actuated from the presser foot for controlling the operation of said power operated positioning means to position said device and thereby to determine the amount of thread measured from the supply in accordance with the thickness of the work.

58. A lockstitch shoe sewing machine having, in combination, stitch forming devices including a hook needle, a work support, a presser foot movable toward and from the work support, a presser foot lock including a presser foot locking element movable with the presser foot, and means for locking said element to lock the presser foot against the work, a thread measuring pull-off, actuating means for the pull-off, a device for modifying the operation of said actuating means to vary the amount of thread drawn from the supply, power operated positioning mechanism operable during that part of each stitch forming cycle when the presser foot is locked against the work to position said device, and adjusting means actuated from said presser foot locking element for controlling the operation of said power operated positioning mechanism to position said device and thereby to determine the amount of thread measured from the supply in accordance with the thickness of the work.

59. A lockstitch shoe sewing machine having, in combination, stitch forming devices including a hook needle, a work support, a presser foot movable toward and from the work support, a presser foot lock including a locking element positioned in accordance with the thickness of the work, a thread measuring pull-off, actuating means for the pull-off, a device for controlling the operation of the pull-off to vary the amount of thread drawn from the supply, a power operated positioning mechanism to position said device including a bracket movable about an axis extending transversely in the plane of movement of said element and having an oscillatory movement between two limiting positions in each sewing cycle, a three-cornered lever pivotally connected at one corner to said bracket, connections pivotally connected to a second corner of the lever for positioning said device, said pivot being located substantially on the axis of movement of said bracket, and a link connection from the third corner of said three-cornered lever to said locking element and having a pivotal connection therewith substantially on the axis of movement of said bracket, and actuating means

for moving the bracket between one limiting position in which the link is arranged at substantially a right angle to the path of movement of the locking element to permit adjustment thereof in accordance with the thickness of the work, and an alternate limiting position in which said adjustment is transmitted through the three-cornered lever and connections to said device.

60. A shoe sewing machine having, in combination, stitch forming and work feeding devices including a hook needle, a work support, a presser foot movable toward and away from the work, and actuating means for the presser foot including spring means urging the presser foot against the work, means for raising the presser foot to permit the feeding of the work, a presser foot lock operable to lock the presser foot in the spring seated position against the work, and means cooperating with the presser foot lock to permit the presser foot to yield a uniform small amount from said spring seated position.

61. A shoe sewing machine having, in combination, stitch forming and work feeding devices including a needle, a work support, a presser foot movable toward and away from the work, actuating means for the presser foot including means for moving the presser foot yielding against the work and for raising the presser foot to permit the feeding of the work, a presser foot lock operable to lock the presser foot against the work, and means including a positive stop surface arranged to permit the presser foot to rise a uniform small amount from its locked position against the work.

62. A shoe sewing machine having, in combination, stitch forming and work feeding devices including a hook needle, a work support, a presser foot, movable toward and away from the work, and actuating means for the presser foot including spring means urging the presser foot against the work, a presser foot lock, and a presser foot lift cam arranged to lift the presser foot during the work feed, said actuating means including means cooperating with said presser foot to permit a uniform slight yield of the presser foot from its work engaging position against said spring means during a portion only of the time that it is locked against the work.

63. A shoe sewing machine having, in combination, stitch forming and work feeding devices including a hook needle, a work feed element arranged to feed the work while the needle is out of the work, a work support, a presser foot movable toward and away from the work, and actuating means for the presser foot including spring means urging the presser foot against the work, a presser foot lock, and a presser foot lift cam arranged to lift the presser foot during the work feed, said actuating means being constructed and arranged to positively lock the presser foot against the work at the completion of the work feed, and thereafter to permit a slight yield of the presser foot against said spring means during the work piercing and loop drawing stroke of the needle.

64. A shoe sewing machine having, in combination, stitch forming and work feeding devices including a hook needle, a work support, a presser foot movable toward and away from the work, and actuating means for the presser foot including spring means urging the presser foot against the work, a presser foot locking element, a presser foot lift cam, connections controlled by the combined action of the locking element and lift cam for locking the presser foot against the work

and for raising the presser foot against said spring means during the work feed, said cam being constructed and arranged to positively support the presser foot in locking position against the work, and thereafter to permit a slight yield of the presser foot during a portion only of the time that it is locked against the work.

65. An outsole shoe sewing machine having, in combination, stitch forming and work feeding devices including a shoe supporting horn, a hook needle, a presser foot movable toward and away from the horn to engage the work, means for feeding the work while the needle is retracted therefrom, actuating means for the presser foot including spring means urging the presser foot against the work, a presser foot lock, and a presser foot lift cam arranged to lift the presser foot during the work feed, said actuating means being further constructed and arranged to positively clamp the presser foot against the work as the needle enters the work, and thereafter to permit a slight yield of the presser foot against said spring means during the work piercing and loop drawing stroke of the needle.

66. An outsole shoe sewing machine having, in combination, stitch forming and work feeding devices including a hook needle, an awl at the side of the work with the needle and arranged to feed the work, a work support, a presser foot arranged to hold the work against the work support, and actuating means for the presser foot including spring means urging the presser foot against the work, a presser foot lock, a presser foot lift cam arranged to lift the presser foot during the work feed, said actuating means being further constructed and arranged to positively clamp the presser foot against the work as the awl is withdrawn and the needle enters the work, and thereafter to permit a slight yield of the presser foot against said spring means during the work piercing and loop drawing stroke of the needle.

67. An outsole shoe sewing machine having, in combination, stitch forming and work feeding devices including a hook needle, an awl at the side of the work with the needle and arranged to feed the work, a shoe supporting horn, a presser foot movable toward and away from the work, and actuating means for the presser foot including spring means urging the presser foot against the work, a presser foot locking element, a presser foot lift cam, connections from the locking element and lift cam cooperating to lock the presser foot against the work and to lift the presser foot during the work feed, said lift cam being constructed and arranged to positively lock the presser foot against the work as the awl is withdrawn, and thereafter to permit a slight yield of the presser foot against said spring means during the work piercing and loop drawing stroke of the needle.

68. An outsole shoe sewing machine having, in combination, stitch forming and work feeding devices including a hook needle, an awl at the side of the work with the needle and arranged to feed the work, a shoe supporting horn, a presser foot movable toward and away from the work, and actuating means for the presser foot including spring means urging the presser foot against the work, a presser foot locking element, a presser foot lift cam, connections from the locking element and lift cam cooperating to lock the presser foot against the work and to lift the presser foot during the work feed, said lift cam being constructed and arranged to permit a slight yield of the presser foot against said spring means

during the work piercing and loop drawing stroke of the needle.

69. An outsole shoe sewing machine having, in combination, stitch forming and work feeding devices including a hook needle, an awl at the side of the work with the needle and arranged to feed the work, a shoe supporting horn, a presser foot movable toward and away from the work, and actuating means for the presser foot including spring means urging the presser foot against the work, a presser foot lock, a presser foot lift cam, an actuating link having intermediate its length a connection to the presser foot, at one end a connection to the presser foot lock, and at its other end a connection to the presser foot lift cam, means for releasing the lock to permit adjustment of the link about its connection with the lift cam to force the presser foot against the work, said lift cam being constructed and arranged to cooperate with said presser foot lock to positively lock the presser foot against the work during retracting movement of the awl, and thereafter to permit a slight yield of the presser foot against said spring means during the work piercing and retracting stroke of the needle.

70. A shoe sewing machine having, in combination, a rotatable work supporting horn, a whirl located in the tip of the horn having the thread delivery orifice thereof eccentric to the axis of rotation of the whirl, driving connections for the whirl including a hollow driving member supported concentric with the axis of rotation of the horn and through which thread is supplied to the whirl, connections for driving the whirl from the driving member at the same speed, and guiding means for the thread arranged to compensate for the tendency of the whirl to tighten and slacken the thread including a guide member having an eccentric bearing on said driving member, and means to prevent rotation of said guide member with the driving member.

71. A shoe sewing machine having, in combination, stitch forming and work supporting devices including a hook needle, a work support, a presser foot movable toward and away from the work, a driving and stopping mechanism for the machine, power means operative in stopping the machine to raise the presser foot, a manual control element and connections therefrom rendered operative by a partial movement of said element to engage the presser foot against the work, and by a further movement of said element to start the machine, and by the return movement of said control element from either of said positions to render said power means operative to raise the presser foot independently of whether the machine was started.

72. A shoe sewing machine having, in combination, stitch forming and work supporting devices including a hook needle, a work support, a presser foot movable toward and away from the work, a driving and stopping mechanism for the machine arranged to stop the machine with the needle withdrawn from the work, a thread lock, and actuating means for the thread lock, power means operative in stopping the machine to raise the presser foot and release the thread lock, a manual control element and connections therefrom rendered operative by a partial movement of said element to engage the presser foot against the work and to permit the closing of the thread lock, and by a further movement of said element to start the machine, and by the return movement of said control element from either of said positions to render said power means operative to

raise the presser foot and to release the thread lock independently of whether the machine was started.

73. A shoe sewing machine having, in combination, stitch forming and work supporting devices including a hook needle, a work support, a presser foot movable toward and away from the work, driving and stopping mechanism for the machine, and power means operative in stopping the machine to raise the presser foot comprising a cam continuously driven independently of whether the machine is running, a follower member movable into and out of operative relation with said cam and connections rendered operative by movement of the follower member under the influence of the cam to raise the presser foot, means for locking the follower in position with the presser foot raised from the work, spring means tending to shift the follower into operative relation with its cam, a detent member arranged to prevent movement of the follower into operative relation with its cam, and means controlled from said driving and stopping mechanism to move the detent member to inoperative position only when the machine has stopped, a control element for starting and stopping the machine, and connections controlled by said control element in starting the machine to release the follower from said locking means and to shift the follower out of the path of said cam and controlled by said control element in stopping the machine to permit the movement of the follower into operative relation to its cam.

74. In a shoe sewing machine having stitch

forming and work feeding devices including a hook needle, a driving and stopping mechanism for the machine which comprises a driven shaft, a braking member, a clutch member on the shaft, means acting in timed relation to the angular motion of the shaft to cause the clutch to engage the braking member to stop the machine with the needle withdrawn from the work, and yieldable supporting means for the braking member arranged to permit the braking member to yield slightly with the clutch member and driven shaft in stopping the machine, and thereafter to return the braking member together with the clutch member and driven shaft in a reverse direction.

75. In a shoe sewing machine having stitch forming and work feeding devices including a hook needle, a driving and stopping mechanism for the machine which comprises a driven shaft, a clutch member on the shaft, a relatively stationary braking member cooperating therewith, means acting in timed relation to the rotation of the shaft to shift the clutch member against the braking member to stop the machine with the needle withdrawn from the work, and a yieldable connection for supporting the braking member including a V-shaped detent, and spring means acting thereon arranged to permit the braking member to yield slightly with the clutch member and driven shaft, and thereafter to return the braking member together with the clutch member and driven shaft in a reverse direction.
